UNITED STATES PATENT OFFICE

BURNHAM C. STICKNEY, OF HILLSIDE, NEW JERSEY

PRINTING PRESS

Application filed March 27, 1926. Serial No. 97,846.

This invention relates mainly to web-perfecting rotary printing presses, especially those in which stereotypes or electrotypes curve around a revolving cylinder.

For printing forms in repetition along a web, especially where there are several forms side by side, as, for example, in printing fan-fold webs or other continuous stationary, it is usual to employ a printing cylinder of such diameter that it can be used to advantage for a certain limited assortment of sizes of forms. The length of the page often equals the circumference of the cylinder; sometimes it is half the circumference, sometimes a third, or a fourth. Accordingly one, two, three or four similar forms are printed repetitiously at each revolution of the cylinder. This gives an enormous output in a short time; but there is the drawback that it becomes necessary to duplicate, triplicate or quadruplicate the electrotype page several times. This is obvious, since the travel of the web at each revolution must exactly equal the circumference of the cylinder, and hence it is necessary to fill up the web with printed matter for substantially its entire travel. There is incurred expense and delay in preparing the duplicate stereotypes or stereotypes, and in adjusting and making ready the duplicates upon the type cylinders. Moreover, it is usual for the web to pass through a second printing couple to perfect the same, and registry must be secured of the printing on one side of the web with that on the other side. This is especially true where the work is intended for use in typewriting machines, inasmuch as a web is usually folded longitudinally into many plies, all of which are manifolded by the typewriting machine, and hence the lines or blanks thereon must be in register throughout the width of the web, on both its sides. Usually the time during which the press is revolving is very small in comparison with the length of time required to get the press ready.

One of the main objects of the invention is to overcome these difficulties, and make it practicable to print forms of any size on a web, and perfect the web, while securing accurate register, and even using only one form

without duplication, thereby reducing the cost of electrotyping or stereotyping, and shortening the time required for getting the press ready. While in thus printing from single forms the press may lack the great productive capacity of the presses which use duplicate forms, still the improved press will operate at sufficiently high speed for practicable purposes, and it can be made ready in much less time than usually required. Moreover, in some cases it is feasible to use duplicate forms on the improved press, if so desired.

In order to avoid the necessity of using a form which is equal to the entire cylinder circumference, or else to an aliquot fraction thereof, the expedient is devised of stopping the web at the conclusion of each impression, and permitting the cylinders of the printing couples, etc., to revolve idly, each cylinder completing its revolution and arriving at the point where the impression of the next type form on the web is to begin, whereupon the web starts up again, and travels in unison with the printing couples, until the conclusion of the printing thereon of a second transverse row of the same forms, whereupon the web is again snubbed, and so on. Thus a form of any dimension may be employed, whether an aliquot or aliquant portion of the circumference of the printing cylinder.

In order to cut down the time in which the web intermittently stands idle, the diameter of the cylinders in the printing couples is reduced below the point usual in web-perfecting presses, say to a diameter of 6 or 8 inches, thus permitting a maximum form length of say 15 to 20 inches, and also permitting the use of duplicate forms, if desired, in some cases. But the forms may be used singly of any circumferential extent with the capacity of the cylinder.

The power device for intermittently advancing the web is located at the delivery side of the perfecting printing couple, and is in the form of feed-rolls, which are constantly revolving at the same speed as the printing couples, and which are separated automatically at intervals by means of a cam. Both feed-rolls constantly revolve, even while they

are separated, so that they act accurately on the web. It will be understood that one cam may be substituted for another, both for arresting and starting the sheet, so as to accommodate forms of different lengths.

5 The web is stopped after the impression of each form, and held still until the completion of the revolution of the printing couple, whereupon the web advances to print the next form. The stopping device may be controlled by a single circular cam connected to the driving gear of the press. At the delivery end of the press the power feed-roll device alternately grips the web to advance it synchronously with the revolutions of the printing couples, and then releases the web at the completion of the printing of each form. This clamping and releasing of the web-feeding rolls may be timed properly with reference to the closing and opening of the web-stopping device at the introductory end of the machine.

10 Power rolls feed the web steadily into the press from the supply-spool, and a take-up roll distends a web-loop that forms between said in-feeding rolls and the devices which control the intermittent feeding movements of the web. Similar power rolls deliver the web from the press. Both the in-feed and the 15 out-feed rolls run uniformly and equally, but at lower speed than the printing cylinder. The speed of said slow rolls is regulatable to accord with the rate at which the web is filled up by the printing forms.

20 35 The printed web may loop idly before it reaches said delivery rolls. One of the delivery rolls may be provided with serrated knives for producing longitudinal lines of perforation in the web, or otherwise longitudinally cutting or weakening the same.

40 45 The delivery rolls may be connected by gearing to the intake rolls, so that the web may be delivered from the press for rewinding or other purposes at the same speed as it is taken into the press. This speed needs to be varied to accommodate forms of different lengths, as the speed will be less where the form is short. For this purpose there may be used a speed-regulating device, as, for instance, a pair of cones and a belt, one of the cones being driven from the driving train of the press.

50 55 In order to provide for proper registry when perfecting the web, so as to accommodate variations in the lengths of the type forms, there is provided between the two type cylinders a compensator, which is not simply the usual corrective device, but has an extraordinary range of sweep or adjustment, 60 the length of idle web between the printing cylinders being made thereby to equal a multiple of the form length, whatever the latter may be. While this idle length of web, for example, may consist of four long forms, in 65 one position of the compensator, it may con-

sist of a dozen short forms in another position of the compensator. Or the compensator may be set to increase or decrease the length of idle web to five forms of another length, or six forms of still another length, 70 or a greater number of forms of other lengths. In other words, the distance from the printing point of one couple to the printing point of another printing couple is fixed, and the length of each form is usually aliquant to 75 said distance, but the length of the idle web between said printing points may be varied by said compensator, so that the length of each form shall be an aliquot part of said length of idle web.

80 Another aliquot compensator, in the form of a power-driven roll, is provided in a loop or web between the second printing couple and the transverse perforating couple. It is preferred to permit adjustment and also keep this compensator constantly revolving, and hence it is carried upon arms mounted upon a rock-shaft, and upon the rock-shaft is a gear which drives a gear upon the compensator-shaft; said driving gear being connected in the driving train of the press, so that at all positions the compensator is power-driven.

85 90 To insure proper registration of the forms on the same cylinder, and also to provide for simple and quick placing of the forms upon the cylinder, it is a feature of the invention that the entire set of forms for each cylinder is stereotyped or electrotyped in one piece, the casting curving considerably more than half way around the cylinder. If an electrotype, it may be cast flat and then converted into a tubular shape by rollers. The type tube is slipped endwise upon the cylinder, the slot in the tube being of sufficient width to enable 100 it to pass over a neck or arm on the framework, in the end of which the printing cylinder is journaled. After the form is thrust upon the cylinder, it is rotated independently thereof to bring it to right printing position 105 thereon, and then it may be held on by means of straps or otherwise. All of the type forms being originally placed in a single chase and so stereotyped or electrotyped, it is evident that the forms on each cylinder may be made 110 in perfect register with one another as a preliminary to stereotyping or electrotyping, and that the same registration will persist at the printing operation, thus reducing the cost of making the press ready, and reducing 115 its idle periods.

120 125 The stereotype or electrotype forms are preferably held on the cylinders by means of straps, which are tightened around the forms by means of nuts, to which the two ends of each strap are attached. The nuts are threaded upon screws, which are rotated so as to tighten the strap. Each strap with its connections is bodily adjustable along the cylinder, and as many straps being employed 130

as may be required. Since all of the forms in each tube are a single unit, they maintain their relative arrangement, so that one adjustment of a single tube suffices for all the forms. Auxiliary tube-fastening devices may be employed if desired.

To solve the problem of accommodating fan-fold webs, which in some cases may be nine feet in width, while using a printing cylinder of small diameter and a cylinder-axle which is weak in proportion to its length, there is devised a midway stiffening journal for each of the cylinders in each printing couple. That is, each of the four cylinder-shafts has a rigid support about midway between its ends, this support being fixed upon the framework of the press, whereby the lengthy shaft is prevented from springing at its middle from the pressure of the printing operation. This central support is made possible, notwithstanding that the press is capable of printing a fan-fold web filling the entire width of the press, by taking advantage of the fact that in the fan-fold web-perfected operation, the impressions of the forms fall alternately upon opposite faces of the web, considered transversely thereof; or in other words, each fold of the fan-folded web is usually printed on only one face. The midway supports for the cylinders in one couple are therefore placed where they will occupy one of the unprinted columns about midway of the web. The midway supporting arms for the cylinders in the other printing couple are placed at a point where no printing is done upon the opposite face of the fan-fold web. One set of cylinder-supports is therefore offset relatively to the other set of midway supports, but nevertheless the entire fan-fold web can be printed. If it is desired to print upon all parts of a web, then the width of the web should not exceed four or five feet; a single sheet being capable of passing by the midway supports or arms. Any width of fan-fold web between four feet and nine feet may be printed by arranging the midway typed forms first with proper reference to said supporting arms, and then proceeding to add the forms to the left and right for the full width of the web, whatever it may be.

There may be run through the press either a web of a width to fill the entire press, or two single-width webs side by side, or one single-width web upon either side of the press. For said wide web the two sections of the aliquot compensator between the printing couples may be brought into exact register, so as to serve as a single compensator while each may be adjusted independently of the other for narrow webs. Each side of the press has its own in-feeding and out-feeding slow rolls, aliquot compensators, intermittent web-feeding devices, etc., permitting such adjustment that long forms may be printed upon

one web, while short forms are being printed upon another web, the adjustment at each side of the press being independent of that at the other side. For example, a thousand feet of web may be delivered by the press at one side, while five hundred feet are being delivered by the other side, notwithstanding that the printing couples move in unison throughout the press.

It will be understood that at each side of the press there may be printed either one web or a series of narrow webs or ribbons side by side upon unlike webs, for the purpose of assembling them all into a single multiple-ply web after delivery thereof from the printing press; or entirely unrelated jobs may be taken printed on one side of the press, while other unrelated jobs are being printed on the other side of the press, the forms on each side being all of one length.

In providing for the printing of two webs side by side, one at each side of the midway supports, provision is made for independent aliquot compensation of the web at one side from that of the web at the other side of the press. Therefore, the aliquot compensator arranged between the printing couples is divided into left-hand and right-hand sections, each adjustable independently for the printing of forms of different lengths; and the same is true of the aliquot compensator between the second printing couple and the transverse perforating couple; whereby one web may be printed with long forms and fed rapidly through the press, while another web may be printed with short forms and fed more slowly through the press, all of the aliquot compensators on each side of the press being independent of those on the other side. The compensating device between the second printing couple and the transverse perforator couple may be in the form of a cylinder or roll, which is power-driven and therefore constantly revolving; but the paper remains stationary at the required intervals, inasmuch as it rests but lightly upon this revolving compensator, and is not unduly tensioned or dragged thereby.

In preparing the impression cylinder for printing, a sheet or wrapping of strong hard paper may be cemented upon the cylinder for its entire length. Upon this may be cemented a vulcanized pure-rubber blanket which is highly tensioned and therefore extremely hard. Upon this rubber blanket may be cemented another sheet of tough hard paper, and upon this second sheet may be cemented a second layer of highly tensioned soft vulcanized pure rubber; the ends of all being secured in a depression in one side of the cylinder. This blanket may be encased smoothly in a layer or layers of lead, which may be thin, as, for instance, tea lead, or it may be thicker and more substantial, and may form a self-sustaining segment of a tube.

Over this lead layer may be wrapped a layer of thin highly tensioned rubber, and over this rubber may be placed one or two layers of strong, smooth tympan paper. The effect is to bring out the lines of the types, making the printing very clear, without liability of smearing or smudging, and to compensate in large measure for unevennesses in the heights of the types, and for wear or slight injury to the types; and in many cases overlaying and underlaying will be found unnecessary, and in any case the time required therefor may be substantially reduced.

A press is also adapted for economical book-printing, even for runs of moderate length, inasmuch as the make-ready operation is shortened by the use of the lead, which is hard so as to insure the proper degree of pressure between the type and the paper, which is also sufficiently plastic to accommodate itself to inaccuracies in the height and surface of the types, whereby clear type-impressions are secured. The rubber cushion under the lead conduces to bringing up the type-impressions clearly, and also to reducing or avoiding the indenting or peening of the lead by the type-impressions, whereby the same lead can be used for long runs, and even can be used for a succession of runs of different kinds of work, so that a new lead layer or tube is not necessary for each new job on the press. The outer layer of rubber also tends to bring up the type clearly, both layers of rubber being very hard, because of their tensioned condition, so as to secure the proper pressure of the type upon the work-web, while said rubber layers, notwithstanding their hardness, are yielding and elastic. These two layers of rubber and intervening layer of lead, combined with the outer layer of hard smooth tympan paper, make an excellent impression surface for a printing press, because it adapts itself to different conditions of types in the same form, and permits various depths of impressions upon the work-sheet, without the fault of blurring the type-impressions.

It is the usual practice to employ inking rollers capable of inking the printing cylinders for the entire length of the latter, and these rollers on account of their great length are heavily built, and it is the practice to make them of greater diameter, all of which is objectionable; and further objection arises because of the difficulty of printing some of the forms in different colors from others on the same side of the web. The rollers are expensive, and a slight defect at any point usually makes it necessary to replace an expensive roller.

To overcome these and other objections, and to expedite the operation of getting the press ready, there are provided sets of inking rollers, and usually one set is provided for each of the forms which are printed side by

side upon the web. If the fan-fold web, for example, is to be folded up into eight plies, four of which plies are printed on one side with a succession of forms, and four plies printed on the other side with a succession of forms, then there will be employed preferably eight sets of inking rollers, each with its own ink fountain. These inking sets, however, are made adjustable longitudinally of the printing cylinders, so as to accommodate forms of different widths, and also to permit locating the forms in any desired points on the cylinders. While in the illustrations each of the inking rollers is shown of the length for one form, it is obvious that the inking rollers may be made each of a length of two forms, thereby bridging the space between the two forms, or even three forms in some cases. There are used light rollers of small diameter, which are cheap and not liable to fatal injury. Injury to one roller is not serious, because it can be cheaply replaced, without replacing other inking rollers in the same or other sets. Each set of rollers is mounted upon a carriage or frame which is adjustable along guideways provided upon the framework of the press, and wherever adjusted the carriage may be clamped. Each fountain may carry the same colors as the other ink fountains, or a different color, thus giving a wide range of differences in colors to be simultaneously printed. A single distributing roll may be made to answer for the entire length of each printing couple, and may be driven by power, and each of the ink-roller carriages may have one or more rolls to run upon this common distributing roll. The ink is taken from the fountain in the individual carriage and transferred by an individual roll to the main distributing roll at any point where the roll carriage is adjusted, and other rolls on each carriage may also run upon the power distributing roll. The surface speed of the power distributing roll may be higher, for example twice the surface speed of the printing cylinder, thereby doubling the extent to which the ink is distributed; and an individual transfer roll running at high speed upon a distributing roll is shifted over to one of comparatively low speed upon the form rolls.

Said power distributing roll is common to all the carriages, and the same is true of a cam-shaft which extends the length of the press and controls the individual transfer of ink from any fountain to the power distributing roll, and also the transfer from the power-driven high-speed distributing rolls to the form rolls.

In using the press for book-printing, the original type forms may be made usually with two pages extending around each type cylinder, the lines reading longitudinally of the cylinder, and the width of the webs depending upon the number and the width of the page forms. In book-work preferably two

70

105

110

115

120

125

130

webs are used simultaneously, printing, for example, two rows of eight pages each on each of the cylinders, thus printing thirty-two pages on each side of the web or sixty-four pages in all, said sixty-four pages occupying the length of only two pages on the web. The longitudinal perforating of the web may be employed as an aid in folding the same longitudinally into fan-fold form, and the transverse perforations on the web may be used in aiding to cross-fold the fan-folded web back and forth as it emerges from the longitudinal folding mechanism, thus forming a pack with thirty-two pages in each of the cross-folds. The transverse perforations aid not only in cross-folding the web, but also in severing each sixty-four page signature from the end of the folded web, preparatory to binding the same into book form.

Preferably there is provided means for transversely perforating the web at the top of each form, or for providing a weakened line at such points for convenience in tearing the web into its ultimate forms, and for other purposes. This transverse portion or weakening is effected automatically by means of a pair of rollers, which are power-driven and properly timed, about the same as if it formed a third printing couple, so that the perforating or weakening line will appear at the proper point near the first line of printing on each form. An aliquot compensating device is also provided between the second or perfecting printing couple and the transverse perforating couple, and is adjustable to divide the distance between the contacting point of the second printing couple and the contacting point or line of the perforating couple into aliquot parts, each equal to the desired length of form.

In order to provide for the relative adjustment of certain single-width compensators, it is necessary that each be mounted for swinging movement independently of the other, and this makes it convenient to place each compensator upon a pair of rock-arms. These rock-arms, some of which project between the ends of the compensating rolls, which are arranged end to end upon the press, make an obstacle where it is desired to print a wide fan-fold web. To avoid this obstacle, there is mounted between said pair of compensators and said transversely-perforating couple an independent compensator, which is the full width of the press and equal to the width of the widest fan-fold web. This wide compensator, of course, is mounted upon rock-arms and is power-driven in the same manner, and a wide web is passed over this long compensator, leaving the other compensators to work idly. When narrow webs are used, they may be passed over said short compensators and the long compensator runs idly. The long compensator may be adjusted to get the required aliquot length of web between the sec-

ond printing couple and the transverse perforator couple.

It is desired in many cases to punch holes in each printed form for registering the same in the typewriting machine and elsewhere; and to secure this result the transverse perforating couple is also provided with a hole-punching cylinder, this cylinder being the companion to the transverse perforating cylinder. The holes are punched by the set of radial punches mounted at any desired intervals along the punching cylinder. This set of punches is unadjustable circumferentially of the cylinder and punches always in the same position; but an adjustment of the transverse perforating knife relatively to the hole-punching cylinder may be effected by circumferentially adjusting the perforating knife. This circumferential adjustment may be adjusted for each knife-section, one section being used at one side of the press and the other at the other side of the press, the two sections being brought into line when it is desired to perforate a full-width line, but the sections being independently adjustable when dissimilarly printed webs are being run through the two sides of the press.

Other features and advantages will herein-after appear.

Figure 20 shows book-paging diagram of 25 front and back of a single-width web-section.

Figure 21 shows the printed web in fan-folded and partly open condition, and shows how the perfected web is composed of a repetition of the section seen at Figure 20.

Figure 22 is a sectional bottom view taken 30 at about the line 22 of Figure 3.

Figure 23 is a diagram or development of the screw mechanism connecting the ends of one of the straps which hold the stereotype 35 upon a type cylinder.

Figure 24 is a view of the strap.

Figure 25 shows a cross-section, longitudinal section and plan of one of the detachable punches which are individually adjustable 40 longitudinally of the punching cylinder.

A single-width web 21, of about half the width of the press seen at Figure 6, is led up at the right-hand side of the press between type and impression cylinders 22, 23 45 of the first printing couple, Figure 3, and then up between the type and impression cylinders 24, 25 of the second or upper printing couple, whereby the web is perfected. From thence it is led up around a compensating roll 54 and down to a pair of punching and perforating cylinders 27, 28, from which it passes to feed-rolls 29, 30 at the rear or delivery end of the press. These fed-rolls 50 co-operate with a web-snubbing jaw or clip 31 55 at the intake side of the press, to control the stopping and starting of the web, while the printing cylinders and the feeders 29 and 30 constantly revolve at uniform speed, as well as the cylinders of the perforating couple 60 27, 28. At Figure 3 the jaw 31 is shown open, permitting the web to advance through the press. The intermittent advance of the web is caused by the rolls 29, 30, the latter of which is held firmly against the former 65 at intervals by means of a cam 32 at the

right-hand side of the press. Upon the cam rides a roll 33 which is provided upon an arm 34 that is fixed to a rock-shaft 35, from which depend bail arms 36 carrying said roll 30.

The cam 32 is detachably mounted upon the right-hand end of power shaft 37 of the constantly revolving cylinder 27, and for its greater part is concentric with said shaft,

and so maintains the feed-rolls 29, 30 temporarily in contact, and thus determines the length of each printed section of web. The cam has a depressed portion 38, and it will

be seen that when the roll 33 falls into said depressed portion, the web-feeding roll 30 separates from the feed-roll 29, thus releasing

70

the web. At the same time the clip 31 is caused by a spring 39 to snap against a stationary jaw 40, the web being thus gripped

75

in a vise, so that the web is suddenly and effectively arrested or snubbed, and accuracy

80

of form-register and equality of length of the web-sections are secured. The clip 31 is connected to the feed-roll 30 for simultaneous movement, so that at the release of the

85

web when either opens, the other closes upon the web. The spring 39 operates on an arm 41 fixed upon a rock-shaft 42, which carries arms 43, between which the clip 31 extends;

and extending oppositely from the rock-shaft

42 is an arm 44, to which is pivoted the lower end of a right-hand pull link 45, whose upper end is pivoted at 46 to the arm 34. After traversing the depressed portion 38 of the cam, in which it is held by spring 39, roll

90

33 rides again upon the elevated portion 32 of the cam. The movement of the roller out of the depressed portion of the cam is accom-

95

panied by an opening movement of the clip 31 and a closing movement of the feed-roll 30, which is forced by cam 32 against the

100

power-driven feed-roll 29, whereby the web is advanced at a speed which equals the surface speed of the printing couples, whose diameter equals that of feed-roll 29. The

105

cam 32 may be removed and other cams of different lengths substituted therefor, to lengthen or shorten the step-by-step feed of the web, and hence alter the length of the

110

printed web-sections, or accommodate different kinds of work. The length of the elevated part 32 of the cam corresponds with the length or circumferential extent of the

115

form, which, of course, may be made of any desired dimension within the capacity of the printing cylinder. It is therefore necessary

120

to use only one printing form, regardless of its circumferential extent, since, after said form prints, the web remains motionless until the printing couples, etc., complete their

125

revolutions, whereupon the web again advances between the printing couples to receive perfecting impressions on its opposite side, while receiving a fresh impression upon its

130

first side. There is thus a saving in the cost of setting up and duplicating the forms, and

135

5 a saving in the cost of getting the press ready, since only a single form has to be made ready for each page. The press is capable, however, of printing a duplication of short forms at each revolution of the cylinders.

10 The link or rod 45 may be lengthened or shortened by means of a turn-buckle 45^a, so as to secure accuracy and co-operation of the web-releasing and biting devices at the intake and delivery ends of the press.

15 Inasmuch as the forms may vary in length (circumferentially), the longest one being four or five times as long as the shortest one, a multiple-form or aliquot compensating device is provided between the printing couples, said compensating device, for example comprising a bar or apron which extends the width of the web between the printing couples, and may be adjusted sufficiently to compensate to 20 the required extent for the difference in the length of the forms, the compensator-bar or section at the right side of the press being numbered 47, Figures 3 and 6. This difference is not necessarily equal to the difference in length between the shortest form and the longest form, inasmuch as two, three or four successive small forms printed on the web may be taken as a unit in considering the extent of adjustment of the aliquot compensator 25 47. Therefore the difference between the shortest reach of web at this point and the longest reach would need to equal only a little in excess of the circumferential printing field of the type cylinder 22 or 24. The greatest 30 length of web between the printing couples may equal about twice the circumference of the printing cylinder, or less. The adjustment may be effected by means of a hand wheel 48, secured upon a shaft 49, having at 35 its inner end a pinion 50, meshing with rack teeth 51 formed upon horizontal rods 52 that are suitably guided in brackets 53 and carry the compensator-bar 47 at their outer ends, Figures 3, 6, 10.

40 An aliquot or multiple-form compensator is also provided between the perfecting printing couple and the punching and perforating cylinders 27, 28. This compensator may be in the form of a roll 54, Figures 3, 6. It is 45 preferably a power roll, having a shaft 55, whereby it is mounted in swing arms 56 extending from a hollow shaft 57, upon which is also secured a worm-wheel or segment 58, with which meshes a worm 59 operated by a hand-wheel 60 supported upon a fixed bracket 61 on the right-hand portion of the framework. By turning the wheel 60, the arms 56 may be swung up and down in unison, thereby extending or reducing the length of web 50 between the perfecting printing couple and the perforating cylinders, until each form or transverse web-section equals an aliquot part of said length; the range of adjustment being as great as that of the compensator-bar 55 47.

At the intake or bottom end of the press, the paper is led in from a roll (not shown) and passes first between slow power-driven feed-rolls 62, 63, Figures 3, 6, rotating at uniform speed; and the paper-supply roll may 70 be provided with the usual brake, to keep proper tension upon the web advancing to said feed-rolls 62, 63. From said slow feed-rolls the web is led over a vibratory take-up and tension roll 64, Figures 3 and 17, which 75 is carried upon arms 65 that are fixed upon a transverse rock-shaft 66, from which extends an arm 67, to which is attached a tension spring 68. It will be perceived that since the web in the press advances intermittently, 80 while the feed-rolls 62, 63 revolve slowly at uniform speed, the tension roll 64 operates as a take-up, and vibrates to and fro while the printing proceeds. The spring 68 maintains a constant tension on the web, in co-operation with a take-up and tension roll 69 at the delivery side of the feed-rolls 29, 30. Said roll 69 may be carried upon arms 70 that project from a rock-shaft 71, and the web tension may be maintained by a spring 72, which 85 pulls on an arm 73 also secured upon said rock-shaft 71. The web 21 passes from the high-speed feed-rolls 29, 30 over said tension roll 69, and thence to the bite of a pair of power-driven delivery feed-rolls 74, 75, Figures 3, 15. These delivery rolls move at uniform speed at the same rate as the roll 63, being connected thereto by a gear-train including top pinions 76, 77, a vertical shaft 78 and bottom pinions 79, 80, Figure 6. Feed-rolls 75 at its inner end may be carried upon a midway rear bracket 80^a rising behind the web from one of the flanges 115. Roll 62 at its inner end may be journaled in a midway arm 80^b on transverse bar 80^c of the framework, 90 the bar and arm being within the first loop of double-width web, Figure 3.

95 The speed of the feed-roll couples 62, 63 and 74, 75 may be jointly and selectively determined by the use of any suitable variable speed device, as, for example, a pair of cone-pulleys 81, 82, connected by an adjustable belt 83, Figure 6. The means of adjusting the belt is not shown, as the adjustment of the belt of a cone-pulley is known. The 100 cone 81 may be fast upon a shaft 84, Figures 3, 6, 15, upon which is fixed a beveled gear 85, driven by a beveled pinion 86 at the top of a general drive shaft 87 (Figures 6, 7, 8) at the gear (left hand) side of the press; said 105 drive shaft having a driving pulley 88. The speed of the cone 81 is uniform. The cone 82 is fixed upon a shaft 89, which carries said pinion 76 and said roll 75. The belt 83 may be adjusted along the cone-pulleys to 110 increase or diminish the speed of the introductory feed-rolls 62, 63 sufficiently to feed the web into the press exactly as fast as it is used up by the co-operation of feed-rolls 29 and 30, cam 32 and web-arrester 31; and 115 120 125 130

since the delivery rolls 74, 75 have exactly the same speed as the rolls 62, 63, it results that the web is fed out of the press at the same speed as it is supplied thereto; while the introductory and delivery tension rolls 64, 69 compensate for any irregularities, and also insure that the web is kept continually under tension, both when traveling and when stationary, and conducing to perfection of the intermittent feed of the web, so that the forms are printed thereon at equal intervals, and consequently assuring registry of the forms upon one side with those upon the other side of the web.

15 After passing over the introductory tension roll 64, the web is led over an apron or bar 90 to pass up between the web-arresting jaws 31, 40, this bar 90 being placed between the tension roll 64 and the introductory feed-
20 roll 63, so as to permit the forming of a tensioning-loop in the web at 91, Figure 3.

As the web rises through the first printing couple, it may pass around a deflector 92, Figure 3, on its way to the compensator 47; 25 and from thence it may pass over a deflector 93 on its way to the perfecting couple 94, 95. The deflector or apron 92 may also serve to strip the web from the type cylinder 22; and a corresponding stripper 96 may be placed 30 at the delivery side of the type cylinder 24.

There are illustrated stereotypes adapted to print fan-fold webs for typewriting use; but the press is not limited to this class of work. In printing fan-fold webs, alternate forms 35 are printed upon opposite sides of the web, so that when the web is fan-folded longitudinally the forms printed thereon face all the same way. Accordingly, Figures 6, 7, the type forms 97 on the lower cylinder 22 40 alternate with the type forms 97 on the upper cylinder 24; whereby columns or forms are printed alternately on opposite faces of the web. As many forms as desired may be cast in the form of a tubular stereotype 97, Figure 16, the type forms being indicated as 97 and the intervening tubular blank or web- 45 portions as 98, the tube fitting upon any of the type cylinders as 22, 24, 97^a or 100^a, Figure 7.

50 It is desired, as conducive to rigidity, accuracy and simplicity, that the cylinder should have bearings directly in the framework of the press, and yet of such a nature as to admit of the use of a tubular form of stereotype. To this end the right-hand side of the press at Figure 6, which is the side opposite to the gear side, comprises a frame which has an integral bearing 99 for the main shaft 100 of the lower type cylinder sections 22, 100^a, 60 this bearing in the form of a boss which may be cast directly upon the side 101 of the frame, and connected to the body of the side frame 101 by means of a relatively narrow neck-portion 102. The longitudinal open-ended slot 103 in the tubular stereotype, Figure 15,

is of sufficient width to enable the tube to be slipped over the boss 99 and over said neck 102 (Figure 18) onto the cylinder 22, where it may be secured by means of straps 104 (Figures 6, 9, 23) passed around the web-portions 98 of the stereotype. When it is desired to remove or replace a stereotype, Figure 18, the press is turned to such position that the longitudinal clearances or cut-aways on the cylinders are together in each couple. Then the stereotype is slipped over the boss 99 and the neck 102, Figures 6, 18, and onto the cylinder 22. The stereotype does not contact with the blanket on the impression cylinder, which, at this time, has its cut-away portion nearest to the type cylinder. The stereotype, having been shoved along the type cylinder to the desired extent, is now revolved upon the stationary cylinder until it reaches the desired rotative adjustment thereon, whereupon the stereotype is fastened by any suitable means, which may include the straps 104. The internal cylindrical diameter of the stereotype may be a shade over the diameter of the type cylinder, so as to give clearance and freedom in thrusting the stereotype onto the cylinder and adjusting it around the same. It will be understood from Figures 4, 5, 6 and 7, that the type forms 97 on lower rear cylinder 22 have a staggered or echelon relation with those on upper front cylinder 24.

The framework of the press may comprise table-portions 105 having legs 106, 107. Upon the table-portions may be adjustably secured, by bolts 108, the bases 109, 110 of frames, each comprising opposite sides 101, 111. The forward frame has a front wall 112, and the rear frame has a vertical wall 113. The impression cylinders may be journaled in bosses 114, Figures 4 and 18, similar to 99 and level therewith and cast directly upon the side frames. To conduce to stiffness of the framework, upper and lower flanges 115 and 116 may be cast therein at the level of the cylinders in each printing couple. The neck-portions or webs 102 are cast directly upon these stiffening flanges, so that the cylinders are properly supported for making the impressions on the paper-web.

Inasmuch as it is desired to print webs of great width by means of impression cylinders and type cylinders of relatively small diameter (say from 6 to 10 inches) and therefore relatively weak, the press is preferably so organized as to provide a midway support for each of the four heavy main shafts 100, 176, 121 and 122 in the printing couples, without making the press unavailable for printing webs of great width. Such a web of course must pass by said midway supports, and it must receive impressions from the type cylinders in the region of said supports. In order to overcome the difficulty of supporting the cylinders under such conditions, advan-

110

115

120

125

tage is taken of the fact that the fan-fold web has on each face alternate printed and blank columns. The printed column on each face of the web is in register with the blank column on the opposite face thereof. At Figure 6, which represents the rear portion of the press seen at Figure 3, and therefore shows the lower type cylinder 22, it will be seen that there are employed two stereotype tubes 97^a, of which the left-hand one has two type forms, and the right-hand one three type forms. It will be noted that the longitudinal spacing of all type forms may be equal. In the space between the second and third type forms, there is a bearing 117 for main shaft 100, which extends unbroken from one side to the other of the press. This bearing 117 corresponds to 99, and is in the form of a suitable neck cast upon a midway ledge 119 projecting forwardly from the rear wall 113 of the framework. Inasmuch as the bearing 117 occupies a space between adjacent forms 97, it will be understood that no impression is to be made at this point by means of the lower printing couple 22, 23; and hence it is permissible to use a fixed bearing 117 in this place. The double-width web may extend the entire distance from side to side of the press, and may be printed by all of the five type forms seen at the lower part of Figure 6, as well as by the five type forms of the upper printing couple seen in Figure 4; the web advancing up past the midway bearing 117.

When the web reaches the upper printing couple, it must receive type impressions upon its opposite face, including an impression in the column or zone which is left blank between the second and third forms 97 in Figure 5. A bearing 120, Figures 4 and 9, for shaft 121 of the upper printing cylinder, which shaft extends the entire width of the press, is therefore provided upon the front midway wall or partition 120^a, at a point directly above the third printing form 97 at Figure 6. This bearing 120 is substantially level with a rear bearing 122, which forms a midway support for the shaft 123 of the two upper impression cylinder sections 25, which taken together extend the entire distance from one side of the press to the other. The impression cylinder 25, it will be understood, is divided into two similar sections mounted and fixed on the same shaft 123. The fixed bearing 122 separates said parts, and is in a zone which is left blank on one face by the printing couple 24, 25, said zone having been filled on the opposite face of the web by the printing couple 22, 23; the web advancing up past both bearings 117 and 122, the staggered relationship of which thus permits the midway supporting of the shafts. Each bearing occupies a zone which is left unprinted on both sides by its associated printing couple, and said bearings 117 and 122 are therefore out of line with each other at Figure 6.

Hence a web may be used which is longer than either of the impression cylinder sections 25, and may extend the full width from one to the other extreme side of the press. The midway bearing 122^a of the lower impression cylinder 23 is in line with 117 but separated therefrom.

When arranging the type pages or forms on the imposing stone, the printer will first arrange suitably the middle type pages with reference to the midway bearings in the press. Then he will arrange all the remaining type pages with reference to these midway pages or forms.

These opposed midway bearings for each printing couple fall short of meeting each other, so that a narrow space is left between them for the upward passage of the web. Moreover, the diameter of each bearing 117, etc., is the same as that of bearing 99, so that a tubular stereotype 97^a, Figures 6, 16, 18, may be slipped over the bearing 99 along the first section of the type cylinder, and then right on over the midway bearing 117 and onto the second or left-hand section of printing cylinder at Figure 6, and there secured. Then another tubular stereotype may be passed over the same bearing 99 and over the first or right-hand section of type cylinder and there secured, the stereotypes extending end to end and working in co-operation to print a single longitudinal row of forms upon the web; the forms on one stereotype being properly aligned with those upon the other, the same as if it were all a single cylinder instead of two sections. The midway support permits the printing of a web up to say eight feet in width, while making it unnecessary to employ printing cylinders of great diameter, as heretofore found necessary in printing wide fan-fold webs.

The foregoing detailed description of intaking and delivery rolls, take-up and tensioning devices, and compensators, has been more appropriate for a narrow or single-width web not reaching to the midway partitions 119, 120^a, then for a double-width web which extends the full width of the press. Two single-width webs may be run side by side simultaneously through the press, one at one side of the partitions 119, 120^a, and the other at the other side thereof, and on either web there may be printed either long or short forms independently of the other; each of the single webs having its own intake, tensioning, intermittent feeding, compensating and delivering devices.

At Figure 6 it will be seen that the intake rolls 62, 63 have counterparts forming extension rolls 125, 126 co-axial therewith, respectively. For each pair of these intake rolls there is provided a separate tensioning device 126^a similar to 64, Figure 17, each tensioning device in the same zone with its associated intake rolls. These rolls are journaled in swing-

arms 65 hinged upon arms 126^b of a bracket 126^c, Figure 17. The bracket is fastened to the framework by thumb screws 126^d or other devices permitting withdrawal of the bracket 5 and its rolls as a unit, and the substitution of the bracket 126^c, Figure 5, having only one roll, which is double length. The delivery roll bracket 126^c, Figure 3, is similar to 126^c, carrying two rolls end to end, and substitutable by a bracket similar to 126^c and carrying a single double-length roll 69, as will be apparent.

At each side of the press there is also a web-arresting clip or snubber. One of them has 15 already been described as comprising jaws 31, 40. The fixed jaw 40 extends the full width of the press, and the right-hand movable jaw 31 has a left-hand counterpart 127.

The left drive roll 126 at Figure 6 is fixed 20 upon a double-length shaft 128, which is connected with a gear train through pinions 129, 130, vertical shaft 131 and pinions 132, 133, (a counterpart of train 76—80) to speed-regulating cones 134, 135, the latter being a power 25 cone, and the same being connected manually by an adjustable belt 136, which is a counterpart of belt 83 at the right-hand side of Figure 6. The left-hand roll shaft 128 therefore revolves at uniform speed at a rate of 30 adjustment determined by the belt 136. The intake drive roll 63 is fixed upon a sleeve 138, to which is fixed said pinion 80, the sleeve 138 being loose, so that the roll 63 may be revolved independently of the roll 126, thereby 35 accommodating two single-width webs passing through the press at different speeds, one at the left-hand side of the press and one at the right-hand side.

The intermittent feeding mechanism for 40 the left-hand web at Figure 6 includes a web-arrester or snubber 127, which is a counterpart of 31 and is mounted on a pair of arms 139 similar to 43, which extend from a rock-shaft 140, similar to 42, carrying an arm 141, from which rises a rod 142, which has a 45 length-adjusting turn-buckle 143 and is connected at its upper end to an arm 144 corresponding with 34 and fixed to a rock-shaft 145. The arm 144 has a roll 146 corresponding to 33 and riding upon a removable cam 147. This cam is similar to 32, but it may have a different length of depression 38, according to the length of the 50 form being printed. As the rock-shaft 145 is vibrated by means of said cam, against the power of a spring (not shown, but similar to 39), arms 148 are vibrated, carrying a shaft 148^a and feed-roll 149 (counterpart of 30) against a power-driven feed-roll 150 (counterpart of 29), Figure 12, on power shaft 185, which extends unbroken for the entire width of the press.

At Figure 6 there is also shown at the left-hand side a compensator 151 forming a counterpart of 47 and adjusted by means of a

wheel 152, shaft 153, pinions 154, 155 and rods 156, which carry the compensator, and have rack-teeth 156^a, Figure 8. The compensator 151 may be set to a different position from 47, as may be needed, if forms of different lengths are being printed upon the different webs. There is also provided at the left side of Figure 6 a compensator roll 158 (counterpart of 54), which may be set to a different position from 54, or to a similar position, as required. At the delivery end of the press, on the left-hand side, a tensioning roll (similar to 126^a at Figure 17) is provided, which is similar to 69 and is similarly mounted and operated, the tension rolls being, of course, independent of each other. The uniformly revolving slow delivery rolls 74, 75 have a counterpart at the left-hand side of Figure 15 in rolls 159 and 160. Either roll may be connected to a shaft 161, on which is fixed the cone 134, which is connected to gear-train 129 to 133 with the intake feed-rolls 125, 126 to revolve at the same speed; it being understood that both intake and delivery rolls are controlled by the same speed-regulating cones 134, 135.

When a double-width web is to be printed, or a web which is too wide to run between the midway partition 119, 124 and either side of the press at Figure 5, the above-described intake, tensioning, intermittent feeding, compensating and delivering devices may be harmonized or set up or reset to form double-length devices for employment with the double-width web.

The intake roll 63 may be fixed by a set-screw 162 to the drive shaft 128, Figures 3, 4, 6, so that the rolls 63 and 126 revolve as one piece, together with the idle companion rolls 62, 125; the pinion 80 being cast off by loosening a set-screw 163 at the lower right-hand part of Figure 6. The speed of the intake and delivery rolls is controlled by the cones 134, 135, while the cones 81, 82 may revolve idly. The intermittent web-feeding cams 32, 147 may be similar, so that the action of the two web-snubbing clips 31 and 127 may be simultaneous, and the same may be true of the two feed-rolls 30, 149. The two compensators 47, 151 for the printing couples may 115 be brought into line so as to operate jointly for the wide web, as if made in a single piece.

Inasmuch as the web cannot pass the arms 56, which are pivoted directly upon the midway partition 124, there may be employed 120 the special double-length compensator-roll 26 extending the full width of the press at Figure 6, over which the full-width web is run; the compensator-rolls 54 and 158 being idle at this time. The two feed-rolls 30 and 149 act in unison to feed the double-width web.

It will thus be seen that either a double-width web or a single-width web may be passed through the press alone and printed 125

upon both sides, and that two single-width webs may be passed through the press together and printed upon both sides, each independently of the other as to length of form.

5 It will also be understood that several very narrow webs may be run side by side through the press at either or both sides of the midway partition, and each web printed upon one side, the length of the forms being the same for all the narrow webs on each side of the midway partition, but independent of the length of the forms of the webs being printed on the other side of the partition.

10 The foregoing description of the compensator-roll 54 and its appurtenances is applicable also to the companion compensating roll 158, which, together with its shaft 158^a, is adjusted independently up and down by means of a hand-wheel 164 and roll 165 operating a worm-wheel 166 mounted upon a top portion 167 of the side frame of the press, Figures 3, 6, 7, 12, 15. The worm-wheel is on one of a pair of arms 168, upon which the roll 158 is swung up and down until the 15 length of the web between the top printing couple and the perforating couple 27, 28 equals a multiple of the length of each form. In other words, each form is an aliquot portion of said length of web. The double-length roll 26 may be similarly adjusted by means of a hand-lever 169, a roll 170, and worm-wheel or segment 171, which is fixed to one of a pair of arms 172, supporting the shaft 173 of the roll.

15 At the gear side of the press, Figures 7, 12, may be mounted the vertical drive shaft 87 with its drive pulley 88 and having a helical gear 174 meshing with a helical gear 175 fixed upon the end of the shaft 100 which carries the sections 22 and 100^a of the type cylinder in the lower couple. This shaft 100 is geared to shaft 176, which carries sections 23, 176^a of the lower impression cylinder, by means of a pair of gears 177, 178. Also fixed 20 on the drive shaft is a helical pinion 179 meshing with a helical gear 180 on shaft 123 of the impression cylinder in the upper printing couple, the cylinder in this couple being connected by gears 181, 182. There is also 25 mounted on the general drive shaft 87 a helical pinion 183 in mesh with a helical gear 184 mounted on shaft 185 of the power feed-roll sections 29, 150 which constantly revolve at uniform speed at the same rate as the 30 printing rolls. The shaft 185 of said sectional roll 29, 150 has a gear 186 meshing with a pinion 187 of the small vibrating feed-roll 149. The shaft 185 may extend the entire width of the press, and carry upon its opposite end a gear 186^a similar to 186 and meshing with pinion 187^a on the shaft of vibrating feed-roll 30 and similar to 187.

35 Also on said drive shaft 87 is a helical pinion 188 meshing with a helical gear 189 on shaft 37 of punching cylinders 27, 305;

this shaft 37 also having a gear 190 meshing with a gear 191 upon the perforating cylinder 28; said shaft 37 being also used for driving the timing cams 32, 147 of the intermittent web-feeding mechanism, and the cams being individually removable from said shaft for substituting other cams to suit the work in hand.

40 At the upper part of said drive shaft is a beveled pinion 192 meshing with a beveled gear 193, which is fixed to a pinion 196, loosely journaled on the rock-shaft 195, which carries the arms 172 carrying the shaft 173 of double-length compensator roll 26; said pinion 196 meshing with a pinion 194, which is fixed upon said shaft 173 of said roll 26, whereby the latter may be power-driven at all up-and-down adjustments of the roll about the axis 195.

45 The framework includes a midway ledge 195^a at the top of the rear wall 113, this ledge including bearings for members 57, 195, 74, 35 and 28 at Figure 3. Said ledge may be in line with the lower midway partition 119, but is discontinuous or spaced therefrom, the ledge occupying a position within the loop of double-width work-web descending from compensator 26 to and around take-up roll 69 and leading up over feed-roll 75. Roll-shafts 37 and 185 may have a midway support 195^b in line with 195^a and rising from a cross-bar 195^c of the framing. This support 195^b rises within the uppermost loop of the double-width web, and is in front of ledge 195^a and separated therefrom to afford a passage for 50 said web.

55 At the top of the drive shaft pinion 86, similar to 192, uniformly drives the gear 85 upon the shaft 84, so that the latter is constantly revolving, together with the two cone-pulleys 81, 135 thereon, and, at all adjustments of either roll 54, 158, the arms which carry said rolls being fixed to sleeves 199, through which said shaft 84 extends, and there being also fixed upon said shaft 84 a pinion 200 meshing with a pinion 201 and corresponding, respectively, to 196, 194, so that the roll 158 is constantly revolved on all up-and-down adjustments thereof; there being also provided upon the right-hand end 60 of said shaft 84 a similar pinion 202 meshing with a pinion 203 on the shaft 55 of the roll 54.

65 The web in entering the press is advanced at uniform speed from the brake-supply roll by means of the slow introductory feed-rolls 62, 63, and then passes around the take-up and tension roll 64 and around the guide 90, a loop forming between said guide 90 and said take-up roll, which vibrates during the 70 operation of the press, as the loop shortens and lengthens always maintains tension upon the web. The web ascends between the snubbing jaws 31, 40, and thence between the cylinders 22, 23 which form the first printing 75

70

125

130

couple, and then around the aliquot take-up 47, and thence up between the cylinders 24, 25 of the second perfecting printing couple, and thence up around the aliquot 5 compensator 26 or 54, dropping between the punching and perforating rolls 27, 28 to the bite of intermittent feeding rolls 29, 30. From said intermittent feed-rolls the web loops down and up around take-up 10 and tension roll 69, being passed out of the press by the slow uniform power feed-rolls 74, 75. There is illustrated only one form on each printing cylinder considered circumferentially, and this form may be, for 15 example, from four to fifteen inches in depth, the latter extending around the cylinder to its full capacity; but in any case the cams 32 and 147 are proportioned to such depth of the form. If the form extends a great distance 20 around the printing cylinder, then a cam is used which has a long dwell portion 32, holding the power feed-roll 30 against the power feed-roll 29 to feed the web (at printing cylinder speed) while it is being printed by the 25 forms, and a relatively short depression 38 is releasing the feed-roll 30 after the completion of the printing of one form and before the printing of the succeeding form begins. The web remains stationary during this 30 interval, being held by the clamp 31 against the jaw 40 under the control of the same depressed portion 38 of the cam. The feed-roll 30 releases the web at the delivery end of the press as the snubber 31 closes upon the web at 35 the intake end of the press. It will be understood that while the web is in stationary condition it is kept under tension by the roll 69, and that while the web is traveling it is kept under tension by the roll 64; said rolls 40 sufficing to put the desired tension upon the web, which at the printing operation does not travel at very high speed, say at the rate of six thousand impressions per hour, although not limited to that speed. It will be understood 45 therefore that a succession of forms 97 of similar dimensions extends along each printing cylinder, said forms making up two stereotypes, the stereotypes in the form of tubes, and that the web remains stationary 50 during a predetermined portion of the revolution of the printing cylinder, which portion may be very small or very large, according to the depth of the form. Hence it is unnecessary to prepare more than one line of 55 forms, so that duplication thereof, as heretofore practiced in order to fill up the printing cylinder, is rendered unnecessary. The labor of getting the press ready is reduced by using only one row of forms, even though 60 each form extends only a small fraction of the circumference of the printing cylinder, and great saving is effected in getting the press ready, so that a run of five thousand or even less may be performed economically 65 by reason of the saving in the preparation

of the forms and in getting the press ready.

A further advantage is that the original type forms may be all made up in one chase and stereotyped as a unit, whereby each form is brought into exact relation or register with the remaining forms while they are in the condition of types, and no realignment is rendered necessary after the forms are on the press, whereby a further saving is effected in the time and cost of making ready; the usual loss of time in making ready a press of this character being serious, inasmuch as the press is capable of a large output while running; and its output is cut off while it is being made ready. Moreover, when the stereotype is cast, it fits directly upon the cylinder, and may be moved to a stop thereon and there secured, without the need of adjusting the same either longitudinally or circumferentially, thereby effecting a further reduction 70 in the time in which the press must stand idle. The forms may be arranged in the type chases in their final relation to one another, and the four tubular stereotypes may be cast therefrom and placed directly upon the press, 80 with little or no attention to making the forms ready after they have been slipped into place. When the length of the form is very small, it results that the web stands still during a large proportion of the operation of the press, but the time saved in getting ready is very great, and the time required for finishing an order of an ordinary number of copies would be only an hour or two, 85 with resulting economy, as the loss of time in passing the work through the press is more than made up by the saving of time in making the press ready.

Any suitable method may be employed for fastening the tubular stereotypes upon the cylinders, and one of the fastening means may be in the form of the straps 104, Figures 6, 9, 23 and 24, which, in a variety of ways, may be used to clamp the form, the straps encircling the depressed web-portions 98 of the stereotypes. One method of tightening the straps may be described. The strap has at each end a keyhole-slot 204, and these slots may catch over buttons 205 on nuts 206, which may travel along screws 207, 105 Figures 9 and 23, mounted in ends 208 and rising from a base 209, the latter having midway of its ends a transverse rib 210, which has bearings at 211 for the inner ends of the screws 207. Fixed upon said screws are bevelled pinions 212 facing each other and also in proximity to each other, so as to be capable of simultaneous rotation by means of a pinion 213. This pinion may be formed upon a removable key shown at Figure 9, said key comprising a stem 214, carrying said pinion 213, and a cross-bar or handle 215. The end of the stem extends through the pinion 213 and fits in a shallow bearing 216 in the rib 210, 115 so that by setting the key down, with its point 120

inserted in the bearing 216, the winding of the key will cause the strap pinions 212 to revolve in opposite directions, thereby turning the screws oppositely and causing the nuts 207 thereon to approach each other, thereby tightening the strap. This gives a powerful grip and holds the stereotypes securely and also takes up the loose fit between the stereotype and the cylinder itself. The tubular stereotype may be made thin, as the straps bind it securely to the cylinder, and the stereotype may be accurately and cheaply finished upon its interior cylindrical surface, inasmuch as it is in the form of an open-ended tube. It will be understood that the stereotype or electrotype may be cast without the slot 103. The web may continue throughout the circumference of the stereotype; this extra web-portion 217, Figure 14, being removed and the slot formed as a final step after the stereotype is otherwise finished.

The bases 209 may be set down into a convergent-sided groove or depression 218 extending the length of each printing cylinder, said bases being held in place by the tightening of the straps.

For saving time and improving the quality of the type-impressions, there is employed an improved blanket upon each impression cylinder 23 and 25, Figures 1 and 2. It includes a highly tensioned soft rubber wrapping 219, overlaid by a sheet or tube of lead 220, the latter covered by another highly tension soft rubber layer 221, which is covered by a protecting wear-resisting sheet or superposed sheets of suitable tympan paper 222. The thickness of the composite blanket may be only $\frac{1}{8}$ of an inch, or as much as a quarter of an inch; and some latitude is permissible in the thicknesses of the various layers. The lead conduces to sharpness of impression, and also has a further characteristic that compensates to a certain extent for unevenness in heights of the types or forms on the printing cylinder. It tends to make the printing very sharp and clear, even if the types are worn. If new types and old types are used side by side, the lead tends to compensate for the inequality. The lead is sufficiently resisting to pressure to form a support for the paper as it is being squeezed by the inked types, so that ink is transferred to the paper. But wherever the pressure is excessive, the lead yields locally, owing to its plasticity, thus permitting the neighboring types to print clearly. The lead layer or tube may be in some cases as thick as $\frac{1}{8}$ of an inch, and in other cases may be quite thin; and in some cases it may be made up of two or more layers or wrappings of lead. However, it should be smooth and of uniform thickness throughout. As it will be most used near its advance edge, it may be removed and reversed from time to time, so

as to present relatively fresh portions to the types.

The underlying blanket 219 of soft rubber may be highly tensioned, so as to be both extremely hard and highly elastic. This also aids in making the type-impressions sharp, and in compensating for worn types. Moreover, the rubber blanket 219 forms a cushioning support for the lead, so that the latter does not become unduly indented or punished by the types, if at all. The overlying relatively thin layer 221 of rubber should also be highly tensioned, and also conduces to sharp impressions and to compensation for wear or uneven heights of the types, and it also tends to preserve the lead from undue punishment by the types. The overlying layer or layers 222 of suitable tympan paper protect the rubber and other layers from injury, and may be more frequently renewed than the underlying layers, and it also conduces to the desired quality of type-impressions upon the work-web.

One method of producing a tensioned under layer 219 is to wrap a web of thin vulcanized pure rubber 223 to form a skein, as at Figure 14, around bars 224. This rubber may be of a high quality similar to that used for dental purposes, and upon wrapping the same around said bars, its layers may be cemented together. Then the projecting ends of one bar 224 may be caught under hooks 225, Figures 1 and 13, projecting from the sides 226 of a curved open box 227 that fits within a convergent-sided depression 228 forming the periphery of the impression cylinder; said box being removably secured by screws 229. The ends of one of said bars 224 are caught upon one pair of hooks 225, and then the multiple-ply rubber sheet or blanket is pulled around the cylinder, and the projecting ends of the other bar 224 are caught under similar hooks 225 at the other side of the box, Figure 2. In pulling this blanket around the cylinder, the rubber should be very much distended and packed tightly upon the cylinder, to which it may in some cases be cemented or attached by shellac, to conduce to stability and durability.

In place of the multiple-ply seen at Figure 14, the rubber blanket may be made of a single tube of high-grade rubber, and the bars 224 inserted within the tube, and the same may be stretched and caught in the same manner around the impression cylinder. If desired, the impression cylinder may be first covered by a sheet of hard, tough paper held thereto by shellac; and the rubber may be attached to the paper by shellac or cement. Similar layers of tough paper may be interleaved with the various rubber layers and cemented thereto, thus conducing to stability and durability. The layer of lead may be secured in any suitable manner, as, for instance, by providing it with project-

ing bars 230 to catch under the same hooks 225, Figure 1. This lead blanket should fit tightly and smoothly upon the rubber blanket and should have a true and smooth cylindrical outer face.

6 The outer thin layer of rubber may be provided with similar bars catching in the same manner under the hooks 225, Figure 1. The outer paper layers may be wound upon 10 revoluble tightening rods 232 pivoted in the arcuate ends 233 of box 227, and rotated to tighten the paper by means not shown; rotating devices for tightening tympan paper being known. The entire composite blanket, 15 including the paper, the rubber and the lead, is very hard, and tends to pack under the repeated impressions of the types, and hence to compensate for wear and other unevennesses of the types; so that the usual special 20 "making ready", in the nature of providing overlays for the blanket and underlays for the stereotypes, is reduced or eliminated. This composite blanket may be considerably 25 varied within the scope of the invention, and it is not necessary in all cases to use all portions thereof. Moreover, this feature of the invention is useful on other printing cylinders and in various kinds of presses, including the flat platen variety.

30 Notwithstanding the opening left in the impression cylinder for the blanket-securing box frame 227, the periphery of the cylinder may be made substantially continuous by the use of a segmental filler plate 233^a, Figure 2, 35 extending the length of each cylinder or section, and curved in conformity therewith, and substantially bridging the space in the cylinder which is left open by the inturned blanket ends. This plate may be attached 40 after the blankets are in place, by means of studs 233^b at the ends of the plate, having reduced ends 233^c which are secured in holes in the box and cylinder casting. This conduces to uniform tautness and smooth running and accurate feeding of the web.

45 The great length of the printing couple shafts may render it desirable in some cases to provide for impression adjustment at the midway supporting walls or partitions 50 through which the shafts pass. One form of such adjustment is illustrated at Figure 9, in which the shaft 234 of the upper type cylinder is shown extending through a bearing having the form of a boss 235, of somewhat 55 less diameter than the type cylinder 24, and formed upon the inner end of a stem or shank 236, which fits tightly in a bore 237 in the partition 120^a. The outer end of this stem is indicated at 238. Into the end of the stem 60 is threaded a screw 239, having formed thereon, near its outer end, a flange 240. A cap 241 is fixed upon the framing and confines the screw against endwise movement. By turning the screw in one direction, the 65 stem 236 and bearing 235 are thrust rear-

wardly or to the right at Figure 9, thereby increasing the impression. By turning the screw in the opposite direction, the impression may be decreased at this point. The screw may be provided with a lock-nut 242. 70 It will be understood that each of the four printing couple shafts may be thus adjusted about midway of its length.

75 The outer ends of the shafts may also be adjusted toward and from each other in each printing couple, by loosening the bolts 108 which hold the two standing frames onto the table, and then turning side bolts 244, Figure 7, to draw the cylinders toward each other or separate them, at either end of the press, Figures 4 and 7, the same being secured by lock-nuts 245. Fine adjustment may be secured by the use of co-operating stops 246 in the form of rods, Figure 7, which may be threaded into one of the lugs 247, Figure 4, extending from the sides of the framework, and bearing at its end against the other lug, so that the front and rear frames may be forced apart, together with the cylinders; the bolts 244 then being used to draw the lugs tightly against the stops 246.

80 The plan is discarded, which is common in web presses, of using ink-rollers of about the same length as the type cylinders, because of the objectionably great diameter and weight of said rolls, and their inadaptability to small forms and liability to small injuries which render the whole roll useless; and also because of the difficulty in using 100 more than one color of ink throughout the length of the roll. To overcome these objections and gain further advantages, there is employed a series of ink-roll sets, the rolls in each set being a little longer than the length of a type form 97, and each series of rolls being mounted in a frame and forming therewith a unit, which is settable or adjustable to any desired point or zone along the type cylinder. Sets of units of assorted 105 sizes may be kept in reserve, for use with forms of different lengths. While there is illustrated a unit which is about coextensive in length with one of the forms, it will be understood that the length of any unit may 110 be doubled, or tripled, so as to ink two or more of said forms if desired.

115 An assortment of sizes of units may be kept in reserve, some of fractional size as compared with those illustrated, and some double size, and so on. Each unit may comprise a pair of side plates 248, Figures 3, 6, 9, 11, between which extend inking rollers, several of which may be journaled in the side plates. The side plates may be connected by a top 120 cross-bar 249 and a bottom cross-bar 250, which bars may be integral with the plates. Between the plates may also extend an ink-fountain 251, with its doctor roll 252, which 125 may have a drive ratchet 253 operable by a 130

pawl mechanism 254. It is usual in printing presses to control the feed of ink by means of the pawl mechanism. There is shown a separate pawl mechanism for each roller set, giving individual control. From the doctor roll the ink is taken by a transfer roll 255, which is journaled upon a pair of vibratory arms 256, which are mounted upon a rock-shaft 257 journaled at its ends in the side plates 248. This roll 255 transfers the ink to a distributing roll 258 having a shaft 259 journaled at its ends in the side plates 248. The arms 256 are swung in one direction by means of a spring 260, and in the other direction by means of a power-driven cam-shaft 261, which extends the full width of the press and is common to all the sets of ink rolls at the front of the press. The distributing roll 258 runs upon a power-driven distributing cylinder 262 extending the full width of the press, and also common to all of the inking sets at the front of the press, wherever they are adjusted. Upon this distributing cylinder also run distributing rolls 263 and 264, similar to 258. In contact with the last roll 264 runs a transfer inking roll 265 which may be of relatively great diameter, and mounted upon arms 266 integral with the vibrating arms 256, and swinging up intermittently away from the roll 264 and into contact with a form roll 267. There is also provided another form roll 268, and a third roll 269 rides upon the form rolls. The form and rider rolls may be mounted upon a swiveled frame 270, pivoted between the ends of arms 271 that are fast upon a rock-shaft 272, the end of which are journaled in the side plates 248; a spring 273 keeping the form rolls in contact with the form. Preferably a stop 274 is engaged by an arm 275 integral with 271 and prevents over-swinging of the form rolls. At Figure 9, which shows one of the inking units at the front of the press, the power for driving the inking devices is supplied by a short vertical counter shaft 276, whose lower end has a beveled pinion 277 meshing with a beveled gear 278 fixed upon the shaft 176 of the impression cylinder 23 of the lower couple. A worm 279 on said shaft meshes with a worm-wheel 280, which revolves the cam-shaft 261, at low speed, the shaft 261 being engageable by the rolls 281 on the lower ends of the vibrating arms 256 of the various inking units, so that ink is transferred from all the doctor rolls 252 to all of the distributing rolls 258 in the sets of the inking units, and so that the transfer rolls 255 and 265 are also operated, the cam 261 driving the arms 256 in one direction, and the springs 260 returning the arms towards the right at Figure 9. Also mounted on said shaft 276 is a beveled gear 282, meshing with a beveled pinion 283 upon a shaft 284 of the distributing cylinder 262, which accordingly is effective upon all the distributing rolls 258, 263, 264 in all of the sets, which may be arranged side by side along this part of the press. The distributing cylinder 262 may revolve at twice the surface speed of the type cylinder 24, or at a higher rate, so as to accelerate and promote the distribution of ink; the transfer roll 265 revolving at high speed when riding upon the distributing roll 264, and revolving at low speed when riding upon the form roll 267. It will be seen that owing partly to the large circumference of the roll 265, which is equal to more than half of the height (circumference) of the highest type form, and partly to the speed of distribution secured by the rapid cylinder 262, an even distribution may be secured.

The inking unit frame 248, 249, 250 is adjustable along guide rails 285, 286 formed in the front and rear of the press, extending from the midway walls or partitions to the sides of the press and integral therewith. A sufficient space is left between the upper and lower tracks 285, 286 to permit the inking unit to be inserted between them to its working position, and to be withdrawn from the press. Each unit may be clamped in place by finger-nuts 287 threaded upon studs 288 projecting outwardly from bars 249, 250, said nuts having flanges 289 which catch on the rear sides of ledges 290 that frame the openings in the front and rear walls of the press. The rails 285, 286 lie at some distance inwardly from said ledges 290, to give room for the studs 288 and flanges 289. Each flange 289 is cut away at 291; and, when said cut-away is rotated to horizontal position, the flange clears ledges 290, permitting the withdrawal of the inking unit from the press.

It will be understood that the inking units may employ all the same color of ink, or each may employ a different color independently of the other units, and that the distributing cylinder 262 can accordingly accommodate a succession of different colors received from the different units, without bleeding of color from any unit upon the succeeding type form.

It will be seen that the distributing rolls 258, 263, 264 are all at the left or upper side of the distributing cylinder 262, which remains in the press when the inking unit is detached, so that said rolls are easily withdrawn from the cylinder. In detaching, it is preferable to draw the bottom of the inking unit forwardly until the top roll 264 is forward of the distributing cylinder 262, and then to let the inking unit descend as it is being withdrawn forwardly from the press. The inking rolls in each unit are all of the same diameter and short, and therefore inexpensive and long-lived, and not open to the objection of cumbersomeness, as in the case of rolls which usually extend the entire length of the printing cylinder. Moreover, no more ink is distributed than is necessary, which is an advantage, particularly where only one narrow web is being printed, which

may, in some cases, be only the width of one of the narrow forms seen at 98. Moreover, great convenience is secured, in that a light supply of ink may be arranged for one form, and a heavy supply of ink for another form, as required.

If desired, the screw stud 288 at the upper part of Figure 9 may be made hollow and the nut may be provided with a guide stem extending into the hollow; but the simple form seen at the lower part of Figure 9 is preferred.

The inking devices at the rear of the press for the type cylinder 22 in the lower couple, may be driven directly by the main drive shaft 87, Figure 8, which may have at its bottom end a crown worm 292 meshing with a worm-wheel 293 on a slow cam-shaft 294 corresponding with 261. Above said worm on said shaft may be arranged a helical gear 295, meshing with a helical gear 296 mounted directly upon the shaft 297 of an inking cylinder 298 corresponding with 262. The other inking parts are similar to those already described, as will be understood. Preferably any unit may be used at any part of the press, upper or lower, back or front, the units being interchangeable. Preferably there is used only one screw stud 288 and flange nut 289 at the bottom of each inking unit frame, this single nut having a position midway of the top flange nuts, so that when the nuts are turned, the frame may be securely tightened and proper pressure secured between its rolls and the members of the press with which they contact. Each frame may be guided vertically by means of an outturned ledge 299 formed upon each of the upper tracks 285 in each set of tracks; the upper bar 249 of the ink frame having a recess 300 within which said ledge 299 projects, thus permitting the bar 249 to ride upon said ledge, and thus locating the inking frame properly in the press.

The web may be longitudinally perforated along the fan-fold lines by means of perforating disks or wheels 301 (Figures 3, 6, 7 and 15) set at intervals (determined by spacing collars or otherwise) along the rolls 74, 159, to match the arrangement of type forms 97; these perforating disks pressing into the rolls 75, 160, which may be made of soft rubber, or otherwise adapted to receive the impressions made by the perforating disks. These wheels will perforate either a single-width web or a double-width web as required. If desired, these wheels may be in the form of knives and slit the web into ribbons; and in that case co-operative shearing knife-disks may be fitted upon the rolls 75, 160. These perforators or knives are constantly operating upon the web as it feeds slowly and uniformly between the rolls, thus making continuous perforations or cuts in the web regardless of the repeated starting and stop-

ping thereof on its way through the press. After the paper leaves the perforating rolls, it may be rewound, or, if desired, it may pass through a fan-folding device or other paper-handling apparatus.

The single and double webs may be transversely perforated by means of toothed blades 302, Figure 12, extending along the right-hand cylinder 28 and its left-hand counterpart 303, Figure 19. These blades revolve at uniform speed with said cylinders, and take effect upon the web just as or a little before the printing cylinders begin to print, whereby a little blank space may be left below the line of perforation and above the printed form of the web.

Each cylinder 27 has a peripheral segmental cushion 304, which supports the paper while it is being indented by the knives 302.

Each cylinder 27, 305 may also be utilized for punching round holes in the paper, for use in binding the sheets, or for locating the sheets in a typewriting machine, especially where the web is severed into ribbons, which are then loosely superposed and placed in the typewriting machine. The punches 306, Figures 6, 7, 12 and 25, may be adjustably and removably mounted in a trough-like frame 307, which extends the length of each cylinder and is preferably cast in one piece with the hollow shaft 308 of the cylinder; the frame extending radially to the periphery of the cylinder. Each punch is hollow, being in the form of a tube having a sharp edge at its outer end, and is threaded into a nut 309, the threaded hole 310 of the latter extending entirely through the nut, and the nut having opposite shoulders 311, which take under the corresponding shoulders 311^a on the frame 307. The nut is drawn up against the shoulders when the punch is screwed into the nut, inasmuch as the nut has a broad flange 312 which bears against the outer or top edge of the frame 307. Thus the nut and punch are tightened in the frame and rigidly supported, while the punchings may fall within the frame, which clears itself. Upon loosening any punch, the punch and nut may be slid as a unit along the frame, which terminates in an open slot 313 extending the length of the cylinder. The punch may be screwed entirely out of the nut and another punch substituted, or both the punch and the nut may be slid as a unit out from the slot at the end of the cylinder. It will be seen that universal adjustment of the punches is practicable along the cylinders, and that any number of punches may be employed. The line of punches on the cylinder 27 or 305, is fixed, and the aliquot compensator-rolls 26, 54 or 158 may be employed to secure proper registry between the line of punches 306 and the top edges of the printing form 97. By the same adjustment of said aliquot rolls, the desired registry is also secured between 131

- the printing forms and the transverse perforating blades 302. Nevertheless, the latter are also preferably adjustable individually around the shaft 314, which has gear 191 meshing with gear 190 on shaft 37, Figures 5 and 12. The blades 302 may also be individually adjusted around the constantly-revolving shaft 314, so as to give a sub-variation in the distance between the line of punchings and the line of perforations on the web; the line of perforations being made first and then the line of punchings, and the distance between the two lines being determined by the rotative adjustment of either of the perforating blades 302. To this end each blade is mounted upon a rotatably adjustable frame, including a hollow shaft 316 and a radial flange 317 integral therewith (Figure 12), and both are adjustable around bosses or collars 318, through which the shaft 314 extends; the collars and the shafts 318, 316 together with the flange 317 and the knife 302 revolving as a unit with the cylinder 28. To adjust the blades 302 relatively to the shaft 314, it is only necessary to loosen an ordinary bolt which is threaded through the end of each cylinder and clamps a slotted wing to the cylinder ends, the slot 321 in said wing being to accommodate the bolt which is stationary in the cylinder. Upon adjusting the flange 317 with its blade 302, the blade may be again secured to preserve the adjustment. There may be also provided upon the hollow shaft 316 a cushion 322 to support the paper during the punching thereof by the punches 306 on cylinder 27 or 305.
- At Figure 21 is illustrated a succession of sections forming a part of the printed web, the fan-folding of which, after printing, is indicated. In printing the pages of a book, the forms may be made up, for example, in the order seen at Figure 20, although other arrangements may be employed. In this illustration a single web may be divided by transverse perforations into strips, upon each side of each of which may be printed sixteen pages, making thirty-two pages in a strip; Figure 20 showing the opposite faces of the strip. These strips, after printing, are fan-folded while attached to the web, as indicated at Figure 21, and are packed closely together, and after being severed from the web may be folded along a middle line 323, Figure 20, thus making a signature ready for the binder. The numbering of the pages on both faces of the strip is given at Figure 20. The forms for printing the book pages need not fill the entire circumference of the printing cylinder, but may run to any extent around the cylinder; the feeding of the web being governed accordingly by substituting other feeding cams 32 or 147, or both, and making the corresponding adjustments in the various compensators and in the variable speed-cone sets. It is therefore not necessary to make a dif-
- ferent press to fit every size page, as any size may be employed within the capacity of the printing cylinder. If each page is very large, then only a single line of pages needs to be printed upon each transverse strip, and, upon fan-folding the same, a signature will be produced. The lines of perforations facilitate the fan-folding, and the forming of the signature, and the binding of the book. The fold along the line 323 may be readily produced after the fan-folded strip is severed from the web. This will answer also for pages in which the top and bottom direction extends around the printing cylinder and the numbering of the pages may be transposed accordingly, as will be understood.
- Variations may be resorted to within the scope of the invention, and portions of the improvements may be used without others.
- Having thus described my invention, I claim:
1. In a printing press, the combination with a printing couple, of co-operative power-driven web-advancing rolls at the delivery side of the printing couple, means for separating said rolls automatically at every revolution of the printing couple, co-ordinated means on the intake-side of the printing couple for intermittently stopping the web, a single power-driven cam controlling both the web-advancing and web-stopping means, movable arms whereon one of said advancing rolls is mounted, means to enable said cam to control the movements of said arms, said stopping means including a movable web-arresting jaw and a stationary jaw co-operative therewith, and connections from said movable jaw to said cam, said connections including a pivoted arm which rides upon the cam, and a link connecting said pivoted arm to said web-arresting jaw, said pivoted arm co-operating with said roll-carrying arms to separate the web-advancing rolls as the web-jaws are closed. 100
  2. In a printing press, the combination with a printing couple, of co-operative power-driven web-advancing rolls at the delivery side of the printing couple, means for separating said rolls automatically at every revolution of the printing couple, co-ordinated means on the intake-side of the printing couple for intermittently stopping the web, a single power-driven cam controlling both the web-advancing and web-stopping means, movable arms whereon one of said advancing rolls is mounted, means to enable said cam to control the movements of said arms, said stopping means including a movable web-arresting jaw and a stationary jaw co-operative therewith, and connections from said movable jaw to said cam, said connections including a pivoted arm which rides upon the cam, a link connecting said pivoted arm to said web-arresting jaw, said pivoted arm co-operating with said roll-carrying arms to separate the web-advancing rolls as the web-jaws are closed. 110

arms to separate the web-advancing rolls as the web-jaws are closed, and a spring tending to close said web-jaws.

3. In a printing press, the combination with a printing couple, of co-operative power-driven web-advancing rolls at the delivery side of the printing couple, means for separating said rolls automatically at every revolution of the printing couple, co-ordinated means on the intake-side of the printing couple for intermittently stopping the web, a single power-driven cam controlling both the web-advancing and web-stopping means, movable arms whereon one of said advancing rolls is mounted, means to enable said cam to control the movements of said arms, said stopping means including a movable web-arresting jaw and a stationary jaw co-operative therewith, and adjustable connecting means between the cam and the web-arresting jaw.

4. In a printing press, the combination with a printing couple and means for revolving the same continuously at uniform speed, of intermittent means at the intake-side of the press for stopping the web during continued revolution of the printing couple, means at the delivery side of the printing couple for intermittently advancing the web at the same speed as the printing couple, slow power intake-rolls rotating continuously at uniform speed for feeding the web to the printing couple, and a vibratory take-up looper-device between said power rolls and said printing couple.

5. In a printing press, the combination with a printing couple and means for revolving the same continuously at uniform speed, of intermittent means at the intake-side of the press for stopping the web during continued revolution of the printing couple, means at the delivery side of the printing couple for intermittently advancing the web at the same speed as the printing couple, slow power rolls rotating continuously at uniform speed to deliver the web from the press, and a vibratory take-up looper-device between said delivery rolls and the printing couple.

6. In a printing press, the combination with a printing couple and means for revolving the same continuously at uniform speed, of intermittent means at the intake-side of the press for stopping the web during continued revolution of the printing couple, means at the delivery side of the printing couple for intermittently advancing the web at the same speed as the printing couple, power intake-rolls for feeding the web to the printing couple, a vibratory take-up looper-device between said power rolls and said printing couple, power rolls to deliver the web from the press, a vibratory take-up looper-device between said delivery rolls and the printing couple, and power means for driv-

ing all of said intake and delivery rolls at the same speed, but at lower speed than the printing couple.

7. In a printing press, the combination with a printing couple and means for revolving the same continuously at uniform speed, of intermittent means at the intake-side of the press for stopping the web during continued revolution of the printing couple, means at the delivery side of the printing couple for intermittently advancing the web at the same speed as the printing couple, power intake-rolls for feeding the web to the printing couple, a vibratory take-up looper-device between said power rolls and said printing couple, power rolls to deliver the web from the press, a vibratory take-up looper-device between said delivery rolls and the printing couple, power means for driving all of said intake and delivery rolls at the same speed, but at lower speed than the printing couple, and means for regulating the speed of said intake and delivery rolls to accord with the rate at which the web is filled up by the forms printed thereon.

8. In a printing press, the combination with a printing couple and means for revolving the same continuously at uniform speed, of intermittent means at the intake-side of the press for stopping the web during continued revolution of the printing couple, means at the delivery side of the printing couple for intermittently advancing the web at the same speed as the printing couple, power intake-rolls for feeding the web to the printing couple, a vibratory take-up looper-device between said power rolls and said printing couple, power rolls to deliver the web from the press, a vibratory take-up looper-device between said delivery rolls and the printing couple, power means for driving all of said intake and delivery rolls at the same speed, but at lower speed than the printing couple, gearing connecting said intake-rolls and said delivery rolls to travel at the same speed, and an adjustable speed-device connected to regulate all of said rolls.

9. In a printing press, the combination with a printing couple and means for revolving the same continuously at uniform speed, of intermittent means at the intake side of the press for stopping the web during continued revolution of the printing couple, means at the delivery side of the printing couple for intermittently advancing the web at the same speed as the printing couple, slow power intake-rolls rotating continuously at uniform speed for feeding the web to the printing couple, and a vibratory take-up looper-device between said power rolls and said printing couple, said take-up device including a roll, and a spring for said take-up roll to maintain the tension upon the web.

10. In a printing press, the combination

with a printing couple and means for revolving the same continuously at uniform speed, of intermittent means at the intake side of the press for stopping the web during continued revolution of the printing couple, means at the delivery side of the printing couple for intermittently advancing the web at the same speed as the printing couple, and means for maintaining tension upon the web both when advancing and when stationary.

11. In a printing press, the combination with a printing couple and means for revolving the same continuously at uniform speed, of intermittent means at the intake side of the press for stopping the web during continued revolution of the printing couple, means at the delivery side of the printing couple for intermittently advancing the web at the same speed as the printing couple, slow power rolls rotating continuously at uniform speed to deliver the web from the press, and a vibratory take-up looper-device between said delivery rolls and the printing couple, said take-up device including a roll, and a spring for said take-up roll to maintain the tension upon the web.

12. In a printing press, the combination with a printing couple and means for revolving the same continuously at uniform speed, of intermittent means at the intake side of the press for stopping the web during continued revolution of the printing couple, means at the delivery side of the printing couple for intermittently advancing the web at the same speed as the printing couple, power intake-rolls for feeding the web to the printing couple, a vibratory take-up looper-device between said power rolls and said printing couple, power rolls to deliver the web from the press, a vibratory take-up looper-device between said delivery rolls and the printing couple, power means for driving all of said intake and delivery rolls at the same speed, but at lower speed than the printing couple, and springs for said take-up rolls to maintain the tension upon the web.

13. In a printing press, the combination with a constantly-revolving printing couple, of a web-advancing device at the delivery side of said couple, a web-snubbing device at the intake side of said couple, means connecting said advancing and snubbing devices so that when either opens the other closes, and means co-operative with said snubbing device for maintaining tension upon the web at the release of the web-feeding couple.

14. In a printing press, the combination with a constantly-revolving printing couple, of a web-advancing device at the delivery side of said couple, a web-snubbing device at the intake side of said couple, means connecting said advancing and snubbing devices so that when either opens the other closes, and means co-operative with said web-feeding couple for maintaining tension

upon the web at the release of said web-snubbing device.

15. In a printing press, the combination with a constantly-revolving printing couple, of a web-advancing device at the delivery side of said couple, a web-snubbing device at the intake side of said couple, means connecting said advancing and snubbing devices so that when either opens the other closes, and means for maintaining tension upon the web both when it is under the control of said feeding couple and when it is under the control of said snubbing device.

16. In a printing press, the combination with a constantly-revolving printing couple, of a web-advancing device at the delivery side of said couple, a web-snubbing device at the intake side of said couple, means connecting said advancing and snubbing devices so that when either opens the other closes, and means for maintaining tension upon the web both when it is under the control of said feeding couple and when it is under the control of said snubbing device, said tensioning means including take-up and tensioning rolls or bars over which the web loops at the intake and delivery ends of the press, and springs for said take-up rolls or bars.

17. In a printing press, the combination with a printing couple and means for revolving the same continuously at uniform speed, of intermittent means at the intake side of the press for stopping the web during continued revolution of the printing couple, means at the delivery side of the printing couple for intermittently advancing the web at the same speed as the printing couple, slow power-driven constantly-revolving feed-rolls at the intake and delivery ends of the press, and introductory and delivery tension rolls co-operative with said intake and delivery slow feed-rolls for compensating for irregularities and maintaining the tension on the web at all times, and conducive to accurate registry of the forms upon opposite faces of the web.

18. In a printing press, the combination of a printing couple, a second printing couple for perfecting a web, means for revolving the printing couples continuously at uniform speed, an aliquot compensating device between said printing couples, means at the delivery side of the second printing couple for intermittently advancing the web at the same speed as the printing couples, means at the intake side of the first printing couple for intermittently arresting the web, slow power intake-rolls for feeding the web to the first printing couple, corresponding power rolls for delivering the web received from the second printing couple, means for regulating the speed of said intake and delivery rolls to cause them to rotate continuously at uniform speed, and vibratory take-up and web-tensioning looping devices between said

intake-rolls and the first printing couple and also between the delivery rolls and the second printing couple, and effective to maintain constant tension upon the web.

5 19. In a printing press, the combination with a printing couple and means for revolving the same continuously at uniform speed, of intermittent means at the intake side of the press for stopping the web during continued revolution of the printing couple, means at the delivery side of the printing couple for intermittently advancing the web at the same speed as the printing couple, and means at the delivery side of said printing couple for transversely perforating the web.

10 20. In a printing press, the combination with a printing couple and means for revolving the same continuously at uniform speed, of intermittent means at the intake side of the press for stopping the web during continued revolution of the printing couple, means at the delivery side of the printing couple for intermittently advancing the web at the same speed as the printing couple, 70 means at the delivery side of said printing couple for transversely perforating the web, and aliquot adjustable means for regulating the length of web between said printing couple and said transversely perforating means.

15 21. In a printing press, the combination with a printing couple and means for revolving the same continuously at uniform speed, of intermittent means at the intake side of the press for stopping the web during continued revolution of the printing couple, means at the delivery side of the printing couple for intermittently advancing the web at the same speed as the printing couple, means at the delivery side of said printing couple for transversely perforating the web, and aliquot adjustable means for regulating the length of web between said printing couple and said transversely perforating means. 75

20 22. In a printing press, the combination with a printing couple and means for revolving the same continuously at uniform speed, of intermittent means at the intake side of

25 the press for stopping the web during continued revolution of the printing couple, means at the delivery side of the printing couple for intermittently advancing the web at the same speed as the printing couple, means at the delivery side of said printing couple for transversely perforating the web, and aliquot adjustable means for regulating the length of web between said printing couple and said transversely perforating means, said adjustable means in the form of an adjusting roll over which the web loops. 80

30 23. In a printing press, the combination with a printing couple and means for revolving the same continuously at uniform speed, of intermittent means at the intake side of the press for stopping the web during continued revolution of the printing couple, means at the delivery side of the printing couple for intermittently advancing the web at the same speed as the printing couple, means at the delivery side of said printing couple for transversely perforating the web, aliquot adjustable means for regulating the length of web between said printing couple and said transversely perforating means, said 85

35 adjustable means in the form of an adjusting roll over which the web loops, and power means for revolving said roll.

40 24. In a printing press, the combination with a printing couple and means for revolving the same continuously at uniform speed, of intermittent means at the intake side of

45 the press for stopping the web during continued revolution of the printing couple, means at the delivery side of the printing couple for intermittently advancing the web at the same speed as the printing couple, and means at the delivery side of said printing couple for transversely perforating the web, aliquot adjustable means for regulating the length of web between said printing couple and said transversely perforating means, said 90

50 adjustable means in the form of an adjusting roll over which the web loops, and power means for revolving said roll.

55 25. In a printing press, the combination with a printing couple and means for revolving the same continuously at uniform speed, of intermittent means at the intake side of

60 the press for stopping the web during continued revolution of the printing couple, means at the delivery side of the printing couple for intermittently advancing the web at the same speed as the printing couple, means at the delivery side of said printing couple for transversely perforating the web, aliquot adjustable means for regulating the length of web between said printing couple and said transversely perforating means, said 95

65 adjustable means in the form of an adjusting roll over which the web loops, and power means for revolving said roll.

70 26. In a printing press, the combination with a printing couple and means for revolving the same continuously at uniform speed, of intermittent means at the intake side of

75 the press for stopping the web during continued revolution of the printing couple, means at the delivery side of the printing couple for intermittently advancing the web at the same speed as the printing couple, and means at the delivery side of said printing couple for transversely perforating the web, aliquot adjustable means for regulating the length of web between said printing couple and said transversely perforating means, said 100

80 adjustable means in the form of an adjusting roll over which the web loops, and power means for revolving said roll.

85 27. In a printing press, the combination with a printing couple and means for revolving the same continuously at uniform speed, of intermittent means at the intake side of

90 the press for stopping the web during continued revolution of the printing couple, means at the delivery side of the printing couple for intermittently advancing the web at the same speed as the printing couple, and means at the delivery side of said printing couple for transversely perforating the web, aliquot adjustable means for regulating the length of web between said printing couple and said transversely perforating means, said 105

95 adjustable means in the form of an adjusting roll over which the web loops, and power means for revolving said roll.

100 28. In a printing press, the combination with a printing couple and means for revolving the same continuously at uniform speed, of intermittent means at the intake side of

105 the press for stopping the web during continued revolution of the printing couple, means at the delivery side of the printing couple for intermittently advancing the web at the same speed as the printing couple, and means at the delivery side of said printing couple for transversely perforating the web, aliquot adjustable means for regulating the length of web between said printing couple and said transversely perforating means, said 110

110 adjustable means in the form of an adjusting roll over which the web loops, and power means for revolving said roll.

115 29. In a printing press, the combination with a printing couple and means for revolving the same continuously at uniform speed, of intermittent means at the intake side of

120 the press for stopping the web during continued revolution of the printing couple, means at the delivery side of the printing couple for intermittently advancing the web at the same speed as the printing couple, and means at the delivery side of said printing couple for transversely perforating the web, aliquot adjustable means for regulating the length of web between said printing couple and said transversely perforating means, said 125

125 adjustable means in the form of an adjusting roll over which the web loops, and power means for revolving said roll.

of intermittent means at the intake side of

the press for stopping the web during con-

tinued revolution of the printing couple,

means at the delivery side of the printing

couple for intermittently advancing the web

70

at the same speed as the printing couple,

means at the delivery side of said printing

75

couple for transversely perforating the web,

aliquot adjustable means for regulating the

75

length of web between said printing couple

80

and said transversely perforating means,

adjustable means in the form of an adjusting

85

roll over which the web loops, pivoted arms

upon which said adjusting roll is carried, and

power gearing including both a gear concen-

80

tric with said roll and a gear meshing there-

with and concentric with the pivot of said

arms, to cause the roll to revolve at all ad-

justments of the arms.

24. In a printing press, the combination 85

with a printing couple and means for revolv-

ing the same continuously at uniform speed,

of intermittent means at the intake side of

the press for stopping the web during con-

90

tinued revolution of the printing couple,

means at the delivery side of the printing

95

couple for intermittently advancing the web

at the same speed as the printing couple,

means also at the delivery side of the print-

90

ing couple and revolving at the same speed,

for perforating the web transversely, and an

aliquot compensating device between said

printing couple and said perforating means.

25. In a printing press, the combination 100

with a rotating printing couple, of means

for starting the web and advancing it an

aliquant portion of the circumference of the

printing cylinder at the same speed, means

for stopping the web and holding it sta-

105

tionary during the remainder of the revolu-

tion of the printing couple, means for trans-

versely perforating the web at the delivery

side of the printing couple, and means for ef-

fecting relative aliquot adjustment between

the printing couple and the perforating

means.

26. In a printing press, the combination 110

with a constantly-revolving printing couple,

of a web-advancing device at the delivery side

of said couple, a web-snubbing device at the

115

intake side of said couple, means connecting

said advancing and snubbing devices so that

when either opens the other closes, and means

at said web-advancing device for perforating

the web transversely.

120

27. In a printing press, the combination

with a printing couple and means for revolv-

ing the same continuously at uniform speed,

of intermittent means at the intake side of

the press for stopping the web during con-

125

tinued revolution of the printing couple,

means at the delivery side of the printing

couple for intermittently advancing the web

at the same speed as the printing couple,

means at the delivery side of said printing

130

couple for punching a transverse row of holes in the web.

28. In a printing press, the combination with a constantly-revolving printing couple, of a web-advancing device at the delivery side of said couple; a web-snubbing device at the intake side of said couple, means connecting said advancing and snubbing devices so that when either opens the other closes, means at said web-advancing device for perforating the web transversely, and means at the delivery side of said printing couple for punching a transverse row of holes in the web.

29. In a printing press, the combination with a printing couple and means for revolving the same continuously at uniform speed, of intermittent means at the intake side of the press for stopping the web during continued revolution of the printing couple, means at the delivery side of the printing couple for intermittently advancing the web at the same speed as the printing couple, means at the delivery side of said printing couple for punching a transverse row of holes in the web, and means for effecting adjustment between said printing couple and said punching means.

30. In a printing press, the combination of a printing couple, a second printing couple for perfecting the web, means for revolving the printing couples continuously at uniform speed, means for automatically advancing the web at printing speed during only a portion of each printing couple revolution, and then holding the web stationary during the remainder of such revolution, an adjustable aliquot compensating device over which the web travels between said printing couples, and means at the delivery side of the second printing couple and adjustable relatively thereto for transversely perforating the web and punching a transverse row of holes therein.

31. In a printing press, the combination of a printing couple, a second printing couple for perfecting the web, means for revolving the printing couples continuously at uniform speed, means for automatically advancing the web at printing speed during only a portion of each printing couple revolution, and then holding the web stationary during the remainder of such revolution, an adjustable aliquot compensating device over which the web travels between said printing couples, means at the delivery side of the second printing couple and adjustable relatively thereto for transversely perforating the web, slow power intake-rolls rotating continuously at uniform speed for feeding the web to the first printing couple, a vibratory take-up looper-device between said power rolls and said first printing couple, slow power rolls rotating continuously at uniform speed to deliver the web from the press, and a vibratory take-up looper-device be-

tween said delivery rolls and the first printing couple.

32. In a printing press, the combination with a printing couple and means for revolving the same continuously at uniform speed, of intermittent means at the intake side of the press for stopping the web during continued revolution of the printing couple, means at the delivery side of the printing couple for intermittently advancing the web at the same speed as the printing couple, means at the delivery side of said printing couple for punching a transverse row of holes in the web, power intake-rolls for feeding the web to the printing couple, a vibratory take-up looper-device between said power rolls and said printing couple, power rolls to deliver the web from the press, a vibratory take-up looper-device between said delivery rolls and the printing couple, and power means for driving all of said intake and delivery rolls at the same speed, but at lower speed than the printing couple.

33. In a printing press, the combination with a constantly-revolving printing couple, of a web-advancing device at the delivery side of said couple, a web-snubbing device at the intake side of said couple, means connecting said advancing and snubbing devices so that when either opens the other closes, means at the delivery end of the press for transversely perforating the web, and means at the delivery side of said perforating means for maintaining tension upon the web both when it is under the control of said feeding couple and also when it is under the control of said snubbing device.

34. In a printing press, the combination of a printing couple, a second printing couple for perfecting a web, means for revolving the printing couples continuously at uniform speed, an aliquot compensating device between said printing couples, means at the delivery side of the second printing couple for intermittently advancing the web at the same speed as the printing couples, means at the intake side of the first printing couple for intermittently arresting the web, slow power intake-rolls for feeding the web to the first printing couple, corresponding power rolls for delivering the web received from the second printing couple, means for regulating the speed of said intake and delivery rolls to cause them to rotate continuously at uniform speed, vibratory take-up and web-tensioning looping devices between said intake-rolls and the first printing couple and also between the delivery rolls and the second printing couple, and effective to maintain constant tension upon the web, and transverse web-perforating means between the delivery rolls and the second printing couple.

35. A press for printing extra wide webs, including a framework, a printing cylinder extending from side to side of the framework

and its ends journaled in the framework, and a bearing upon said framework for said cylinder about midway of the ends of the latter, and occupying a zone which is left blank during the printing of the webs, said press including a second or perfecting printing cylinder similarly supported, and having a corresponding midway support out of line with the midway support upon the first cylinder, whereby a web may be run through the press, past said midway supports and printed by said cylinders on both sides.

36. A press for printing extra wide webs, including a framework, a printing cylinder extending from side to side of the framework and its ends journaled in the framework, a bearing upon said framework for said cylinder about midway of the ends of the latter, and occupying a zone which is left blank during the printing of the webs, said press including a second or perfecting printing cylinder similarly supported, and having a corresponding midway support out of line with the midway support upon the first cylinder, whereby a web may be run through the press, past said midway supports and printed by said cylinders on both sides, and impression cylinders co-operating with said printing cylinders and having corresponding supports about midway between their ends.

37. A press for printing extra wide webs, including a framework, a printing cylinder extending from side to side of the framework and its ends journaled in the framework, a bearing upon said framework for said cylinder about midway of the ends of the latter, and occupying a zone which is left blank during the printing of the webs, said press including a second or perfecting printing cylinder similarly supported, and having a corresponding midway support out of line with the midway support upon the first cylinder, whereby a web may be run through the press, past said midway supports and printed by said cylinders on both sides, and impression cylinders co-operating with said printing cylinders and having corresponding supports about midway between their ends, the midway supports for the printing and impression cylinders of each couple being placed at a point where no printing is done upon the opposite face of the web.

38. A press for printing extra wide webs, including a framework, a printing cylinder extending from side to side of the framework and its ends journaled in the framework, a bearing upon said framework for said cylinder about midway of the ends of the latter, and occupying a zone which is left blank during the printing of the webs, said press including a second or perfecting printing cylinder similarly supported, and having a corresponding midway support out of line

with the midway support upon the first cylinder, whereby a web may be run through the press, past said midway supports and printed by said cylinders on both sides, and impression cylinders co-operating with said printing cylinders and having corresponding supports about midway between their ends, the midway supports for said cylinders projecting toward each other from front and back of the press and leaving an intermediate space for the passage of the web.

39. In a printing press, the combination with a main frame, of a printing cylinder journaled therein, said frame having a neck portion in which said printing cylinder has a bearing, said neck portion being of a relatively small dimension and permitting the sliding of an open tubular stereotype or electrotype over the neck portion and onto the cylinder, said press having also a bearing for said printing cylinder about midway of the length thereof, said last-mentioned bearing also having a neck portion over which said tubular stereotype or electrotype may pass when sliding the same onto a second section of the printing cylinder.

40. In a press for simultaneously printing two webs side by side, the combination with a printing couple and a perfecting printing couple, of means between said printing couples for effecting aliquot compensation of each web independently of the other.

41. In a press for simultaneously printing two webs side by side, the combination with a printing couple and a perfecting printing couple, of means between said printing couples for effecting aliquot compensation of each web independently of the other, provision being made for effecting similar compensation for a web extending the full width of the press.

42. In a printing press, the combination with a couple for printing simultaneously webs running side by side, of means for revolving the printing couple continuously at uniform speed, and means at the intake side of the press for stopping each web independently of the other web at every revolution of the printing couple.

43. In a printing press, the combination with a couple for printing simultaneously either a full width web or narrow webs running side by side, or means for revolving the printing couple continuously at uniform speed, means at the intake side of the press for stopping each web independently of the other web at every revolution of the printing couple, and means at the delivery side of the printing couple for intermittently advancing either the full width web or each narrow web independently of the other narrow web at the same speed as the printing couple.

44. In a printing press, the combination with a printing couple through which webs may pass side by side, of means for starting

and advancing each web during different portions of the revolution of the printing couple from the other web, and means for stopping each web independently of the other and holding it stationary during the remainder of the revolution of the printing couple.

45. In a printing press, the combination with a printing couple through which webs may pass side by side, of a couple of power-driven web-advancing rolls at the delivery side of said printing couple for each web, means for separating the rolls in each advancing couple automatically at every revolution of the printing couple independently of the other advancing couple, and co-ordinated means on the intake side of the printing couple for intermittently stopping each web independently of the other.

46. In a printing press, the combination with a printing couple through which webs may pass side by side, of a couple of power-driven web-advancing rolls at the delivery side of said printing couple for each web, means for separating the rolls in each advancing couple automatically at every revolution of the printing couple independently of the other advancing couple, and co-ordinated means on the intake side of the printing couple for intermittently stopping each web independently of the other, power-driven cams independently controlling each of the web-advancing and web-stopping mechanisms.

47. In a printing press, the combination with a printing couple through which webs may pass side by side, of a couple of power-driven web-advancing rolls at the delivery side of said printing couple for each web, means for separating the rolls in each advancing couple automatically at every revolution of the printing couple independently of the other advancing couple, and co-ordinated means on the intake side of the printing couple for intermittently stopping each web independently of the other, power-driven cams independently controlling each of the web-advancing and web-stopping mechanisms, each of said cams substitutable by another cam for limiting the extent of each advance of its associated web.

48. In a printing press, the combination with a printing couple through which webs may pass side by side, of a couple of power-driven web-advancing rolls at the delivery side of said printing couple for each web, means for separating the rolls in each advancing couple automatically at every revolution of the printing couple independently of the other advancing couple, and co-ordinated means on the intake side of the printing couple for intermittently stopping each web independently of the other, said stopping means for each web including a movable jaw and a stationary jaw co-operative therewith.

49. In a printing press, the combination

with a printing couple through which webs may pass side by side, of a couple of power-driven web-advancing rolls at the delivery side of said printing couple for each web, means for separating the rolls in each advancing couple automatically at every revolution of the printing couple independently of the other advancing couple, co-ordinated means on the intake side of the printing couple for intermittently stopping each web independently of the other, power-driven cams independently controlling each of the web-advancing and web-stopping mechanisms, said stopping means for each web including a movable jaw and a stationary jaw co-operative therewith, and independent connections from said movable web-jaws to said cams.

50. In a press for printing webs simultaneously side by side, the combination with a constantly revolving printing couple, of independent advancing devices for each web on the delivery side of the couple, independent snubbing devices for each web on the intake side of the couple, and means independently connecting each advancing device to its associated snubbing device, so that when either opens the other closes.

51. In a press for printing webs simultaneously side by side, the combination with a constantly-revolving printing couple, of independent advancing devices for each web on the delivery side of the couple, independent snubbing devices for each web on the intake side of the couple, means independently connecting each advancing device to its associated snubbing device, so that when either opens the other closes, and means automatically controlling each of said advancing and snubbing devices independently of the other.

52. In a press for printing webs simultaneously side by side, the combination with a constantly-revolving printing couple, of independent advancing devices for each web on the delivery side of the couple, independent snubbing devices for each web on the intake side of the couple, and means independently connecting each advancing device to its associated snubbing device, so that when either opens the other closes, said advancing devices including roll couples, and means for driving said advancing rolls at the same surface speed as said printing couple.

53. In a press for printing simultaneously webs running side by side, the combination of a printing couple including a type-form cylinder having at one end a row of forms for one web and at the other end a row of forms for the other web, the forms in each row extending only partly around the cylinder, and means for causing each web to advance with the printing couple to an extent to enable each web to receive the impression of its own forms, and then to come to rest independently of the other web, and means to

cause each web to remain stationary until the completion of the revolution of the printing couple, thus completing the cycle of operations.

5 54. In a press for printing webs simultaneously side by side, the combination of a printing couple, a second or perfecting printing couple, means for revolving the cylinders of the printing couples continuously at uniform speed, means individual to the webs for automatically advancing them at printing speed each during only a portion of the revolution of each printing couple, and means for snubbing each web independently of the 10 other web, and holding each web stationary during the remainder of the revolution cycle of the printing couples.

55. In a press for printing webs simultaneously side by side, the combination of a printing couple, a second or perfecting printing couple, means for revolving the cylinders of the printing couples continuously at uniform speed, means individual to the webs for automatically advancing them at printing speed each during only a portion of the revolution of each printing couple, means for snubbing each web independently of the other web, and holding each web stationary during the remainder of the revolution cycle of the printing couples, and individual aliquot adjustable compensating devices, one for each web, over which the webs travel between said printing couples, and individual aliquot adjustable compensating devices, one for each web, over which the webs travel between said printing couples.

56. In a press for printing webs simultaneously side by side, the combination of a printing couple, a second or perfecting printing couple, means for revolving the cylinders of the printing couples continuously at uniform speed, means individual to the webs for automatically advancing them at printing speed each during only a portion of the revolution of each printing couple, means for snubbing each web independently of the other web, and holding each web stationary during the remainder of the revolution cycle of the printing couples, power rolls forming a couple for each web to feed it to the first printing couple, and individual take-up looping devices between said power rolls and said first printing couple.

57. In a press for printing webs simultaneously side by side, the combination of a printing couple, a second or perfecting printing couple, means for revolving the cylinders of the printing couples continuously at uniform speed, means individual to the webs for automatically advancing them at printing speed each during only a portion of the revolution of each printing couple, means for snubbing each web independently of the other web, and holding each web stationary during the remainder of the revolution cycle of the printing couples, power rolls forming a couple for each web to feed it to the first printing couple, individual take-up looping devices between said power rolls and said first printing couple, independent of the other set to accord with

devices between said power rolls and said first printing couple, individual power-roll couples to deliver the webs independently from the press, and take-up looping devices between said delivery rolls and the perfecting printing couple.

58. In a press for printing webs simultaneously side by side, the combination of a printing couple, a second or perfecting printing couple, means for revolving the cylinders of the printing couples continuously at uniform speed, means individual to the webs for automatically advancing them at printing speed each during only a portion of the revolution of each printing couple, means for snubbing each web independently of the other web, and holding each web stationary during the remainder of the revolution cycle of the printing couples, individual aliquot adjustable compensating devices, one for each web, over which the webs travel between said printing couples, power rolls forming a couple for each web to feed it to the first printing couple, individual take-up looping devices between said power rolls and said first printing couple, individual power-roll couples to deliver the webs independently from the press, take-up looping devices between said delivery rolls and the perfecting printing couple, and power means for driving all of the intake and delivery rolls at the same speed for each web, but independently of the speed of the corresponding rolls for the other web.

59. In a press for printing webs simultaneously side by side, the combination of a printing couple, a second or perfecting printing couple, means for revolving the cylinders of the printing couples continuously at uniform speed, means individual to the webs for automatically advancing them at printing speed each during only a portion of the revolution of each printing couple, means for snubbing each web independently of the other web, and holding each web stationary during the remainder of the revolution cycle of the printing couples, individual aliquot adjustable compensating devices, one for each web, over which the webs travel between said printing couples, power rolls forming a couple for each web to feed it to the first printing couple, individual take-up looping devices between said power rolls and said first printing couple, individual power-roll couples to deliver the webs independently from the press, take-up looping devices between said delivery rolls and the perfecting printing couple, power means for driving all of the intake and delivery rolls at the same speed for each web, but independently of the speed of the corresponding rolls for the other web, and means for regulating the speed of each set of intake and delivery rolls independent of the other set to accord with

the rate at which the corresponding web is filled up by the forms printed thereon.

60. In a press for printing webs simultaneously side by side, the combination of a printing couple, a second or perfecting printing couple, means for revolving the cylinders of the printing couples continuously at uniform speed, means individual to the webs for automatically advancing them at printing speed each during only a portion of the revolution of each printing couple, means for snubbing each web independently of the other web, and holding each web stationary during the remainder of the revolution cycle of the printing couples, individual aliquot adjustable compensating devices, one for each web, over which the webs travel between said printing couples, power rolls forming a couple for each web to feed it to the first printing couple, individual take-up looping devices between said power rolls and said first printing couple, individual power-roll couples to deliver the webs independently from the press, take-up looping devices between said delivery rolls and the perfecting printing couple, power means for driving all of the intake and delivery rolls at the same speed for each web, but independently of the speed of the corresponding rolls for the other web, gearing connecting the intake-rolls and delivery rolls in each set to travel at uniform speed, and an adjustable speed device connected to operate all of the rolls in each set independently of the other set.
61. In a press for printing webs simultaneously side by side, the combination of a printing couple, a second or perfecting printing couple, means for revolving the cylinders of the printing couples continuously at uniform speed, means individual to the webs for automatically advancing them at printing speed each during only a portion of the revolution of each printing couple, means for snubbing each web independently of the other web, and holding each web stationary during the remainder of the revolution cycle of the printing couples, and means for maintaining tension upon each web independently of the other web, both when it is under the control of its own feeding couple and also when it is under the control of its own snubber.
62. In a press for printing webs simultaneously side by side, the combination of a printing couple, a second or perfecting printing couple, means for revolving the cylinders of the printing couples continuously at uniform speed, means individual to the webs for automatically advancing them at printing speed each during only a portion of the revolution of each printing couple, means for snubbing each web independently of the other web, and holding each web stationary during the remainder of the revolution cycle of the printing couples, and means for maintaining tension upon each web independently of the other web, both when it is under the control of its own feeding couple and also when it is under the control of its own snubber, said tensioning means including take-up and tensioning rolls or bars over which the webs loop at the intake and delivery ends of the press, and springs for said take-up rolls or bars.
63. In a press for printing webs simultaneously side by side, the combination of a printing couple, a second or perfecting printing couple, means for revolving the cylinders of the printing couples continuously at uniform speed, means individual to the webs for automatically advancing them at printing speed each during only a portion of the revolution of each printing couple, means for snubbing each web independently of the other web, and holding each web stationary during the remainder of the revolution cycle of the printing couples, and means co-operating with said snubbing means for maintaining tension upon each web at the release of the corresponding web-advancing couple, independently of the snubbing, tensioning and feeding means for the other web.
64. In a press for printing webs simultaneously side by side, the combination of a printing couple, a second or perfecting printing couple, means for revolving the cylinders of the printing couples continuously at uniform speed, means individual to the webs for automatically advancing them at printing speed each during only a portion of the revolution of each printing couple, means for snubbing each web independently of the other web, and holding each web stationary during the remainder of the revolution cycle of the printing couples, and means for maintaining tension upon each web independently of the other web, both when it is under the control of its own feeding couple and also when it is under the control of its own snubber.
65. In a press for printing webs simultaneously side by side, the combination of a printing couple, a second or perfecting printing couple, means for revolving the cylinders of the printing couples continuously at uniform speed, means individual to the webs for automatically advancing them at printing speed each during only a portion of the revolution of each printing couple, means for snubbing each web independently of the other web, and holding each web stationary during the remainder of the revolution cycle of the printing couples, and means for maintaining tension upon each web independently of the other web, both when it is under the control of its own feeding couple and also when it is under the control of its own snubber, said tensioning means including take-up and tensioning rolls or bars over which the webs loop at the intake and delivery ends of the press, and springs for said take-up rolls or bars.

66. In a press for printing either a wide web or two narrow webs side by side, the combination with a printing couple and a perfecting printing couple, of means between said couples for effecting aliquot compensation for the wide web or for the two narrow webs independently each of the other.

67. In a printing press, the combination with couples for printing either a single web of the full width of the press or two narrow webs side by side simultaneously, of means for revolving the printing couples continuously at uniform speed, and means at the intake side of the press for snubbing either the full width web or each of the two narrow webs independently of each other at every revolution of the printing couples.

68. In a printing press, the combination with couples for printing either a single web of the full width of the press or two narrow webs side by side simultaneously, of means for revolving the printing couples continuously at uniform speed, means at the intake side of the press for snubbing either the full width web or each of the two narrow webs independently of each other at every revolution of the printing couples, and means at the delivery side of the printing couples for intermittently advancing either the full width web or the two narrow webs independently of each other at the same speed as the printing couples.

69. In a printing press, the combination with a printing couple through which may pass either a full width web or narrow webs side by side, of co-operative power-driven web-advancing rolls at the delivery side of the printing couple capable of advancing either the full width web or independently advancing each of two narrow webs, means for separating the rolls in each couple automatically independently of the other web at every revolution of the printing couple, and co-ordinated means at the intake side of the printing couple for intermittently stopping either the full width web or the narrow webs independently of each other.

70. In a press for printing either a full width web or narrow webs side by side simultaneously, the combination of a printing couple, a second printing couple for perfecting the web, means for revolving the cylinders of the printing couples continuously at uniform speed, means between said printing couples for effecting aliquot compensation for either the full width web or two narrow webs independently of each other, means at the delivery side of the perfecting couple for advancing the full width web or the two narrow webs at printing speed during only a portion of the revolution of each printing couple, means for arresting either the wide web or each narrow web independently of the other, and means for holding each arrested web stationary dur-

ing the remainder of the revolution of the printing couples.

71. In a press for printing either a full width web or narrow webs side by side simultaneously, the combination of a printing couple, a second printing couple for perfecting the web, means for revolving the cylinders of the printing couples continuously at uniform speed, means between said printing couples for effecting aliquot compensation for either the full width web or two narrow webs independently of each other, means at the delivery side of the perfecting couple for advancing the full width web or the two narrow webs at printing speed during only a portion of the revolution of each printing couple, means for arresting either the wide web or each narrow web independently of the other, means for holding each arrested web stationary during the remainder of the revolution of the printing couples, and means at the intake side of the press for tensioning and taking up either the full width web or the two narrow webs independently of each other.

72. In a press for printing either a full width web or narrow webs side by side simultaneously, the combination of a printing couple, a second printing couple for perfecting the web, means for revolving the cylinders of the printing couples continuously at uniform speed, means between said printing couples for effecting aliquot compensation for either the full width web or two narrow webs independently of each other, means at the delivery side of the perfecting couple for advancing the full width web or the two narrow webs at printing speed during only a portion of the revolution of each printing couple, means for arresting either the wide web or each narrow web independently of the other, means for holding each arrested web stationary during the remainder of the revolution of the printing couples, means at the intake side of the press for tensioning and taking up either the full width web or the two narrow webs independently of each other, means for holding each arrested web stationary during the remainder of the revolution of the printing couples, means at the delivery side of the press for tensioning and taking up either the full width web or the two narrow webs independently of each other, and take-up devices at the delivery side of the press for straining the web, and effective upon either a full width web or each of two narrow webs simultaneously and independently of each other.

73. In a press for printing either a full width web or narrow webs side by side simultaneously, the combination of a printing couple, a second printing couple for perfecting the web, means for revolving the cylinders of the printing couples continuously at uniform speed, means between said printing couples for effecting aliquot compensation for either the full width web or two narrow webs independently of each other, means at the delivery side of the perfecting couple for advancing the full width web or the two narrow webs at printing speed during only a portion of the revolution of each printing couple, means for arresting either the wide web or each narrow web independently of the other, and means for holding each arrested web stationary dur-

each narrow web independently of the other, means for holding each arrested web stationary during the remainder of the revolution of the printing couples, and means for maintaining the tension either upon the full width web or upon each of the narrow webs independently of each other both when advancing and when stationary.

74. In a press for printing either a wide web or two narrow webs side by side, the combination with a printing couple and a perfecting printing couple, of means between said couples for effecting aliquot compensation for the wide web or for the two narrow webs independently each of the other, the aliquot compensating means being composed of sections, one for each web, and said sections relatively movable into line to serve as a single compensator for the wide web.

75. In a press for printing either a wide web or two narrow webs side by side, the combination with a printing couple and a perfecting printing couple, of means between said couples for effecting aliquot compensation for the wide web or for the two narrow webs independently each of the other, the aliquot compensating means being composed of sections, one for each web, said sections relatively movable into line to serve as a single compensator for the wide web, the compensator sections being mounted one at one side and another at the other side of the press, and the ends of the sections adjoining near the middle of the press.

76. In a printing press, the combination with couples for printing either a single web of the full width of the press or two narrow webs side by side simultaneously, of means for revolving the printing couples continuously at uniform speed, means at the intake side of the press for snubbing either the full width web or each of the two narrow webs independently of each other at every revolution of the printing couples, and means at the delivery side of the printing couples for intermittently advancing either the full width web or the two narrow webs independently of each other at the same speed as the printing couples, the advancing means for the narrow webs being mounted one at one side and another at the other side of the press, and the ends of the web-advancing means adjoining near the middle of the press.

77. In a printing press, the combination with couples for printing either a single web of the full width of the press or two narrow webs side by side simultaneously, of means for revolving the printing couples continuously at uniform speed, means at the intake side of the press for snubbing either the full width web or each of the two narrow webs independently of each other at every revolution of the printing couples, and means at the delivery side of the printing couples for intermittently advancing either the full width web or

the two narrow webs independently of each other at the same speed as the printing couples, the web-snubbing means for the narrow webs being mounted one at one side and another at the other side of the press, and the ends of the web-snubbing means adjoining near the middle of the press.

78. In a printing press, the combination with couples for printing either a single web of the full width of the press or two narrow webs side by side simultaneously, of means for revolving the printing couples continuously at uniform speed, means at the intake side of the press for snubbing either the full width web or each of the two narrow webs independently of each other at every revolution of the printing couples, means at the delivery side of the printing couples for intermittently advancing either the full width web or the two narrow webs independently of each other at the same speed as the printing couples, the web-snubbing means for the narrow webs being mounted one at one side and another at the other side of the press, the ends of the web-snubbing means adjoining near the middle of the press, and web-feeding slow rolls at the intake and delivery ends of the press for either said full width web or said narrow webs, the web-feeding slow rolls mounted at opposite sides of the press, and the ends of said slow rolls adjoining near the middle of the press.

79. In a printing press, the combination with couples for printing either a single web of the full width of the press or two narrow webs side by side simultaneously, of means for revolving the printing couples continuously at uniform speed, means at the intake side of the press for snubbing either the full width web or each of the two narrow webs independently of each other at every revolution of the printing couples, means at the delivery side of the printing couples for intermittently advancing either the full width web or the two narrow webs independently of each other at the same speed as the printing couples, the web-snubbing means for the narrow webs being mounted one at one side and another at the other side of the press, the ends of the web-snubbing means adjoining near the middle of the press, web-feeding slow rolls at the intake and delivery ends of the press for either said full width web or said narrow webs, the web-feeding slow rolls mounted at opposite sides of the press, the ends of said slow rolls adjoining near the middle of the press, and web-tensioning rolls at the intake and delivery ends of the press for each of the narrow webs, said intake and delivery tensioning rolls for the narrow webs being removable and substitutable by rolls suitable for the full width web.

80. The combination with a printing couple, of a second printing couple for perfecting a web, means for revolving said printing

5 couples constantly at uniform speed, and two sets of intake, web-tensioning, intermittent feeding, compensating and delivering devices, one for each of two webs passing side by side through the press, said devices being adjustable for each web independently of the other, and being capable of coordination to suffice for controlling a full width web.

81. The combination with a printing couple, of a second printing couple for perfecting a web, means for revolving said printing couples constantly at uniform speed, and two sets of intake, web-tensioning, intermittent feeding, compensating and delivering devices, one for each of two webs passing side by side through the press, said devices being adjustable for each web independently of the other, and being capable of co-ordination to suffice for controlling a full width web, said 10 web-controlling devices including a compensating roll of a length for a narrow web and also including a compensating roll of sufficient length for a full width web.

82. The combination with a printing couple, of a second printing couple for perfecting a web, means for revolving said printing couples constantly at uniform speed, two sets of intake, web-tensioning, intermittent feeding, compensating and delivering devices, one for each of two webs passing side by side through the press, said devices being adjustable for each web independently of the other, and being capable of co-ordination to suffice for controlling a full width web, said 15 web-controlling devices including a compensating roll of a length for a narrow web and also including a compensating roll of sufficient length for a full width web, and power means for revolving said compensating roll at all adjustments thereof.

83. In a printing press, the combination with a couple for printing simultaneously webs running side by side, of means for revolving the printing couple continuously at 20 uniform speed, means at the intake side of the press for stopping each web independently of the other web at every revolution of the printing couple, means at the delivery side of the printing couple for intermittently advancing each web independently of the other web at the same speed as the printing couple, and means at the delivery side of said printing couple for transversely perforating each web independently of the other.

84. In a printing press, the combination with a couple for printing simultaneously webs running side by side, of means for revolving the printing couple continuously at 25 uniform speed, means at the intake side of the press for stopping each web independently of the other web at every revolution of the printing couple, means at the delivery side of the printing couple for intermittently advancing each web independently of

the other web at the same speed as the printing couple, means at the delivery side of said printing couple for transversely perforating each web independently of the other, and adjustable means for regulating the length 70 of each web independently of the other that extends between said printing couple and said transversely perforating means.

85. In a printing press, the combination with a couple for printing simultaneously webs running side by side, of means for revolving the printing couple continuously at uniform speed, means at the intake side of the press for stopping each web independently of the other web at every revolution of the printing couple, means at the delivery side of the printing couple for intermittently advancing each web independently of the other web at the same speed as the printing couple, and means at the delivery side of said printing couple for transversely perforating each web independently of the other, said perforating means including paired cylinders or rolls, one having perforators and the other having a co-operative pad support for 80 the web, the perforators for one web being adjustable independently of those for the other.

86. In a printing press, the combination with couples for printing either a single web 95 of the full width of the press or two narrow webs side by side simultaneously, of means for revolving the printing couples continuously at uniform speed, means at the intake side of the press for snubbing either the full 100 width web or each of the two narrow webs independently of each other at every revolution of the printing couple, means at the delivery side of the printing couples for intermittently advancing either the full width web or the two narrow webs independently 105 of each other at the same speed as the printing couples, means at the delivery side of the printing couples for transversely perforating either a wide web or each of the narrow 110 webs independently of each other, and independent compensators between said printing couples and said perforating means, for governing said full width web or either of said narrow webs independently of the other.

87. In a printing press, the combination with couples for printing either a single web of the full width of the press or two narrow webs side by side simultaneously, of means for revolving the printing couples continuously at uniform speed, means at the intake side of the press for snubbing either the full width web or each of the two narrow webs independently of each other at every revolution of the printing couples, means at the delivery side of the printing couples for intermittently advancing either the full width web or the two narrow webs independently 120 of each other at the same speed as the printing couples, means at the delivery side of the 125 printing couples for transversely perforating each web independently of the other, and adjustable means for regulating the length of each web independently of the other that extends between said printing couple and said transversely perforating means.

printing couples for transversely perforating either a wide web or each of the narrow webs independently of each other, and adjustable means for regulating the extent of the full width web or each of the narrow webs independently of the other between said printing couples and said perforating means.

88. The combination with a printing couple, of a transverse web-perforating couple, one member of the latter having transverse web-perforating means, and the other member provided with punches for punching a transverse row of holes in the web; said members having means for supporting the web while being perforated and punched, means for effecting adjustment of the transverse perforating means independently of the punching means, and aliquot compensating means between said printing couple and said perforating and punching couple.

89. The combination with a printing couple, of a transverse web-perforating couple, one member of the latter having web-perforating means, and the other member provided with punches for punching a transverse row of holes in the web; said members having means for supporting the web while being perforated and punched, means for controlling either a full width web or two narrow webs each independently of the other, said perforating and punching couples extending the full width of the press, and the web-perforating means including two blades, one for each narrow web, said blades being relatively adjustable, and aliquot compensating means between the printing couple and the perforating and punching couple.

90. In a web printing press, the combination with a printing couple and means for revolving the same continuously at uniform speed, of means for intermittently feeding the web at the same speed as the printing couple, power-driven delivery rolls for the web running at uniform surface speed more slowly than the printing couple, and means upon said delivery rolls for longitudinally perforating the web.

91. In a press for printing either a full width web or a narrow web side by side, the combination with a printing couple and a transverse perforating couple, of aliquot compensating rolls arranged end to end for the narrow webs, arms supporting said rolls for adjustment independently of each other, and a full width compensating roll for the full width web.

92. A press for printing extra wide webs, including a framework, a printing cylinder extending from side to side of the framework and its ends journaled in the framework, and a bearing upon said framework for said cylinder about midway of the ends of the latter, and occupying a zone which is left blank during the printing of the web, said press

including a second or perfecting printing cylinder similarly supported, and having a corresponding midway support out of line with the midway support upon the first cylinder, whereby a web may be run through the press, past said midway supports and printed by said cylinder on both sides, impression-cylinders co-operating with said printing cylinder and having corresponding supports about midway between their ends, and means for effecting relative adjustment of said cylinders about midway of their length.

93. A press for printing extra wide webs, including a framework, a printing cylinder extending from side to side of the framework and its ends journaled in the framework, a bearing upon said framework for said cylinder about midway of the ends of the latter, and occupying a zone which is left blank during the printing of the web, said press including a second or perfecting printing cylinder similarly supported, and having a corresponding midway support out of line with the midway support upon the first cylinder, whereby a web may be run through the press, past said midway supports and printed by said cylinder on both sides, impression-cylinders co-operating with said printing cylinders and having corresponding supports about midway between their ends, means for effecting relative adjustment of said cylinders about midway of their length, and means for independently adjusting said cylinders at their end portions.

94. In a web-perfected printing press, the combination with successive printing couples and means for revolving the same continuously at uniform speed, of intermittent means at the intake-side of the press for stopping the web during continued revolution of the printing couples, a compensating device over which the web travels between said couples, means at the delivery side of the printing couples for intermittently advancing the web at the same speed as the printing couples, and power means to deliver the web from the press, said delivery means moving at uniform speed less than that of the printing couples, means being provided to form a take-up loop between the second printing couple and said delivery means.

95. In a printing press, the combination with a printing couple and means for revolving the same continuously at uniform speed, of intermittent means at the intake-side of the press for keeping back the web during continued revolution of the printing couple, means at the delivery side of the printing couple for intermittently advancing the web, power-driven web-feeding means at the intake and delivery ends of the press, and web-tensioning means effective from the intake to the delivery portion of the web.

96. In a web-printing press, the combination with a rotating printing couple, of means

for starting the web and advancing it an aliquant portion of the circumference of the printing cylinder at the same speed, means for stopping the web and holding it stationary during the remainder of the revolution of the printing couple, power-driven means at the intake end of the press for feeding the web, power-driven means at the delivery side of the press for delivering the web, all of said power-driven means moving at uniform speed less than that of the printing couple, means for forming loops and tensioning the web at the intake portion of the press, and other means for forming loops and tensioning the web at the delivery portion of the press, said loop-forming means distinct from the web itself.

97. In a printing press, the combination with a printing couple, of co-operative power-driven web-advancing rolls at the delivery side of the printing couple, means for idling said rolls automatically at every revolution of the printing couple, co-ordinated means on the intake-side of the printing couple for intermittently keeping back the web, web-advancing means power-driven at uniform relatively low speed at intake and delivery portions of the press, and loop-forming and web-tensioning means between said printing couple and said low-speed web-advancing means at each end of the press.

98. In a printing press, the combination with a constantly-revolving printing couple, of a web-advancing device at the delivery side of said couple, a web-snubbing device at the intake-side of said couple, means connecting said advancing and snubbing devices so that when either is effective the other is idle, web-delivering means power-driven at uniform relatively low speed, and web-tensioning means including a looper between said printing couple and said delivering means.

99. In a printing press, the combination of a printing couple, a second printing couple for perfecting the web, means for revolving the printing couples continuously at uniform speed, means for automatically advancing the web at printing speed during only a portion of each printing couple revolution, and holding the web idle during the remainder of such revolution, uniformly moving power-driven means for feeding in the web uniformly moving power-driven means for delivering the web, web-tensioning means constantly effective throughout the web between said in-feeding means and said delivering means, and means for universally regulating said power-driven means independently of the printing couples during the operation thereof.

100. In a printing press, the combination of a printing couple, means for revolving the printing couple continuously at uniform speed, means for automatically advancing

the web at printing speed during only a portion of each printing couple revolution, and then holding the web back during the remainder of such revolution, means moving at the same speed as the printing couple, for forming a transverse row of perforations in the web, an adjustable aliquot compensating device over which the web travels between said printing couple and said perforating means, slowly moving power-delivery means, and loop-forming and web-tensioning means between said perforating means and said delivery means.

101. The combination with a printing couple and a perforating couple, of means to cause them to revolve at the same surface speed, means for starting and holding back a web during each revolution of the printing couple and holding the web stationary during the completion of such revolution, web-tensioning means at the intake-end of the press, web-tensioning means at the delivery end of the press, and adjustable aliquot compensating means between the printing couple and the perforating couple, of sufficient capacity to render any form length an aliquot part of the reach of web extending from the printing couple to the perforating couple.

102. The combination of a printing couple, a second printing couple for perfecting a web, an aliquot compensating device between said printing couples, a web-perforating couple for perforating the web transversely, an aliquot compensating device between the second printing couple and the transversely perforating couple, power-feeding and web-tensioning means at the intake-end of the press, and power web-advancing and tensioning means at the delivery side of said perforating couple.

103. In a printing press, the combination of a printing couple, a second printing couple for perfecting the web, means for revolving the printing couples continuously at uniform speed, means for automatically advancing the web at printing speed during only a portion of each printing couple revolution, and then holding back the web during the remainder of such revolution, an adjustable aliquot compensating device over which the web travels between said printing couples, means at the delivery side of the second printing couple and adjustable relatively thereto for transversely perforating the web, and web-tensioning means effective from the intake-end of the press to the delivery side of said perforating means.

104. In a printing press, the combination of a printing couple, a second printing couple for perfecting the web, means for revolving the printing couples continuously at uniform speed, means for automatically advancing the web at printing speed during only a portion of each printing couple revolution, and then holding the web stationary during the

remainder of such revolution, an adjustable aliquot compensating device over which the web travels between said printing couples, means at the delivery side of the second printing couple and adjustable relatively thereto for transversely perforating the web, means also at the delivery side of said printing couples for longitudinally perforating said web, power-driven means for delivering the web, and web-looping and tensioning means.

105. In a printing press, the combination with a printing couple and means for revolving the same continuously at uniform speed, of intermittent means at the intake-side of the press for holding back the web during continued revolution of the printing couple, variable means at the delivery side of the printing couple for intermittently advancing the web to different extents at the same speed as the printing couple, power-driven means for delivering the web from the press at uniform low speed, and means for varying the speed of said delivering means independently of the printing couple.

106. A perfecting press for printing short forms on extra wide webs, including a framework, front and back printing cylinders and companion impression-cylinders, each of said cylinders being of minimum diameter and extending from side to side of the framework and each at its ends journaled in the framework, and a bearing upon said framework for each of said cylinders about midway of the ends of each, and occupying a zone which is left blank during the printing of the web, clearance being left between said bearings for the passage of a web whose width equals the length of the printing cylinder, and means for advancing the web intermittently during constant uniform rotation of the cylinders.

107. In a printing press, the combination with a frame, of web-perfecting printing couples supported thereon, each couple including a tubular stereotype-cylinder of substantially minimum diameter and an impression-cylinder, said frame having neck-portions in which said stereotype-cylinders have bearings, each neck-portion being of relatively small diameter and permitting the sliding of an open tube stereotype over the neck-portion and along the cylinder, bearings being also provided upon said frame for supporting each of said stereotype-cylinders about midway of its ends, each of the last-mentioned bearings also having a neck-portion over which a tubular stereotype may pass when sliding from one section of the stereotype-cylinder to the other, means for alternately holding back the web and feeding it at the speed of said printing couples, aliquot compensating means between said printing couples, and means for feeding the web into and out of the machine at uniform speed less than the speed of said printing couples, the speed of the printing couples.

108. In a web printing press, the combination with a printing couple and means for revolving the same continuously at uniform speed, of means for intermittently feeding the impression-receiving field of the web at the same speed as the printing couple, a set of power-driven infeeding rolls for the web, a separate set of power-driven delivery rolls for the web, all of said rolls running uninterruptedly at uniform surface speed more slowly than the printing couple, web-tensioning means co-operative with said delivery rolls between the latter and said printing couple, and maintaining the web constantly under tension between the infeeding and the delivery rolls, and means for universally varying the relative speed between said printing couple and said infeeding rolls and said delivery rolls.

109. A press for printing extra wide webs, including a framework, a printing cylinder extending from side to side of the framework and having its ends journaled in the framework, a journal bearing of relatively small diameter upon said framework for said cylinder about midway of the ends of the latter, and occupying a zone which is left blank during the printing of the webs, said framework having a neck portion of relatively small diameter forming a journal bearing for an end of said printing cylinder, permitting the sliding of an open tube stereotype over said end neck portion and past said midway journal bearing, and an impression-cylinder co-operating with said printing cylinder and having a corresponding journal bearing about midway of its ends, a clearance being left between said midway journal bearings for the travel of a web of a width equal to the entire combined length of the printing cylinder portions.

110. In a printing press, the combination of web-perfecting printing couples, variable means for alternately arresting the web and feeding it at the speed of said printing couples, aliquot compensating means between said printing couples, means for feeding the web into and out of the machine at uniform speed less than the speed of said feeding couples, means for regulating the speed of said feeding means independently of the printing couples, and constantly effective means for tensioning the web longitudinally throughout the length thereof between the infeeding and outfeeding points; said aliquot device being adjustable and having a capacity for causing the circumferential length of any form on a printing cylinder to consist of an aliquot portion of the length of web extending from one printing couple to the other.

111. A printing press for printing extra wide webs, including a framework, a printing cylinder extending from side to side of the framework and having its ends journaled in the framework, there being provided upon

said framework for said cylinder a journal bearing about midway of the ends of the cylinder, said midway journal bearing occupying a zone which is left blank 5 during the printing of the web, an impression cylinder co-operating with said printing cylinder and having a corresponding journal bearing about midway of its ends, and power-driven means for feeding an extra wide 10 web to said cylinders and away therefrom, clearance for the web being left between said midway journal bearings.

112. A press for printing either ordinary width or extra wide webs, including a frame 15 work, a printing cylinder extending from side to side of the framework and having its ends journaled in said framework, a journal bearing upon said framework for said cylinder about midway of the ends of the latter, and 20 occupying a zone which is left blank during the printing of an extra wide web, an impression cylinder co-operating with said printing cylinder and having a corresponding journal about midway of its ends, a clearance 25 being left between said journal bearings for the travel of a web of a width equal to the entire combined length of the printing cylinder portions, means for feeding through said press either a web as wide as the full 30 length of said printing cylinder, or a web whose width is less than the distance from said midway journal to the end of the printing cylinder.

113. A printing press for perfecting extra 25 wide webs, including a framework, perfecting printing cylinders, each extending from side to side of the framework and having its ends journaled in the framework, there being provided upon said framework for each 30 cylinder a journal bearing about midway of the ends of the cylinder, said midway journal bearings occupying zones which are left blank during the printing of the webs, impression cylinders co-operating with said 35 printing cylinders and having corresponding journal bearings about midway of their ends, and power-driven means for feeding extra wide webs to said cylinders and away therefrom, clearances being left between said midway journal bearings for the travel of the 40 webs.

114. In a printing press, the combination 45 of a printing couple including a type-form cylinder having a single row of forms thereon extending only a fraction of the distance around the cylinder, and variably-adjustable means for causing the impression-receiving field of a web to travel coextensively with the printing couple to the desired extent during the printing of said forms, and then to remain stationary until the completion of the cycle of operation of the printing couple, intake means for feeding the web into the press 55 uninterruptedly at uniform slow speed, means to deliver the web out of the press at

the same uniform slow speed, means for regulating the speed of said infeeding means relatively to the printing couple, and also the speed of said delivery means, and web-tensioning means constantly effective 70 throughout the web between said intake means and said delivery means.

115. In a printing press, the combination 75 of a printing couple, a second printing couple for perfecting the web, means for revolving the printing couples continuously at uniform speed, variable means for automatically causing the impression-receiving field of the web to travel at printing speed during only a variable portion of each printing couple revolution, and holding the web stationary during the remainder of such revolution, an adjustable aliquot compensating device over which the web travels between said printing couples, power-driven slowly-moving 80 means for uninterruptedly feeding the web into the press, power-driven slowly-moving means for uninterruptedly delivering the web, means for universally varying the speed of said infeeding means and said delivery 85 means independently of the printing couple while the press is in motion, and constantly effective web-tensioning means for the entire web between said infeeding means and said delivery means.

116. In a printing press, the combination 90 with a frame, of a printing couple supported thereon and including a tubular stereotype cylinder of substantially minimum diameter and an impression cylinder, said frame having a neck-portion in which said stereotype cylinder has a bearing, said neck-portion being relatively thin to permit thrusting a gapped tubular stereotype thereover and to position upon its cylinder, said stereotype cylinder having a longitudinal 95 gap, means to secure the stereotype tube on the cylinder with the tube-gap occupying a position over the cylinder-gap, said impression cylinder having a longitudinal gap and 100 geared to the stereotype cylinder so that the gaps of the two cylinders meet at every revolution, and work-controlling means for causing a work-web to travel intermittently between said cylinders at the same speed as the 105 cylinders, to enable the web to be printed by means of the stereotype, and said means causing the web to stop its travel once in each revolution of the stereotype cylinder, while the gap-portions of the cylinders pass by the 110 web.

117. In a printing press, the combination 115 with a frame, of a printing couple supported thereon and including a tubular stereotype cylinder of substantially minimum diameter and an impression cylinder, said frame having a neck-portion in which said stereotype cylinder has a bearing, said neck-portion being relatively thin to permit thrusting a gapped tubular stereotype thereover and to position 120

upon its cylinder, said stereotype cylinder having a longitudinal gap, means to secure the stereotype tube on the cylinder with the tube-gap occupying a position over the cylinder gap, said impression cylinder having a longitudinal gap and geared to the stereotype cylinder so that the gaps of the two cylinders meet at every revolution, work-controlling means for causing a work-web to travel intermittently between said cylinders at the same speed as the cylinders, to enable the web to be printed by means of the stereotype, and said means causing the web to stop its travel once in each revolution of the stereotype cylinder, while the gap-portions of the cylinders pass by the web, and stereotype and impression cylinders having corresponding longitudinal gaps for perfecting said web, said perfecting stereotype cylinder having thereon a gapped tubular stereotype, and said frame having a relatively-thin bearing-neck to permit said perfecting stereotype to be thrust upon its cylinder; said perfecting cylinders being geared to cause their gaps to pass the web while the latter is stationary.

118. In a printing press, the combination with a frame, of a printing couple supported thereon and including an impression cylinder and a cylinder having a tubular stereotype thereon, said tubular stereotype having a longitudinal gap, and said frame having a neck-portion in which said stereotype cylinder has a bearing, said neck-portion being made thin to permit thrusting the gapped tubular stereotype thereover into position upon its cylinder, means for locating said tubular stereotype circumferentially of its said cylinder, and work-controlling means for causing a work-web to travel intermittently between said cylinders at the same speed as the cylinders, to enable the web to be printed by means of said tubular stereotype, said controlling means causing the web to stop once in each revolution of the stereotype cylinder and remain stationary while the gap-portion of the stereotype tube passes the web.

BURNHAM C. STICKNEY.
